PUNCHING MACHINE

Clair D. Lake, Binghamton, and Francis E. Hamilton, Endicott, N. Y., assignors to International Business Machines Corporation, New York, N. Y., a corporation of New York

Application July 13, 1942, Serial No. 450,730

46 Claims. (Cl. 164—113)

This invention relates to punching machines and more particularly to the type which is adapted for punching tabulating cards which are subsequently used in accounting and billing operations.

The principal object of the present invention is to provide a punching machine with keyboard verifying and card checking arrangements which will not only verify the accuracy of the previous keyboard operations by the operator but will also check the punching effected by the punching machine to determine whether the data punched on the card corresponds to the verified digital setup.

A still further object of the machine closely allied to the principal object of the invention is to provide such arrangements with a mode of operation which will enable the keyboard controlled verifying operations and digital punching verifying operations to be effected in an overlapping sequential operation without holding up the operator so that it is only necessary for the latter to operate the keyboard to set up the data relating to the original record and to repeat the keyboard operations for verifying purposes. It has been the previous practice for the verification of card punching operations by repeat keyboard operations to provide a separate key controlled verifying machine which will determine the accuracy of the card punching operations but such repeat keyboard verifying machines have, according to prior constructions, been constructed as an independent keyboard controlled unit. Hence, for card punching and verifying operations, two machines were necessary; the original key controlled punching machine and the key controlled verifying machine and necessitating two operators to secure the final product. In the key controlled verifying machine the punched card was, however, not analyzed to determine the accuracy of the perforations made by the punching machine and in such forms of machines, the operation of the keyboard of the verifying machine solely determines whether the same keyboard strokes were performed in the card punching machine. While card punching machines have been ordinarily found to be accurate in their card punching operations, in some jobs it is highly desirable and essential from an accounting standpoint to insure by the highest percentage of accuracy that the card punching operations are correctly performed by the machine and correspond with the original data set up. The present machine has been devised to comply with such requirements and by the provision

5 of the key controlled verifying operations and the digital punching card checking operations, the accuracy of the final product is made more nearly certain; and further, any deviation in the repeat keyboard operations and card punching from the original keyboard operations is indicated to the operator in suitable ways so that the reason for the error can be ascertained and corrected.

10 One object of the present invention is to provide a digit storage arrangement which consists principally of banks of storage relays which are set up under a control keyboard; and by the key strokes of the keyboard the various storage columns are successively set up to represent the original data. It sometimes happens that the attention of the operator is diverted, or that the original data is incorrectly read, which will be reflected in an incorrect setting of one of the 15 storage columns of the digit storage arrangement and in order to locate such inaccuracies the present machine includes an arrangement which, by means of repeat keyboard operations, the inaccuracy of the original digit set up may be determined. This preferably consists of a 20 supplemental digit setup controlled by the storage relays and as the repeat key operations are effected the digit entered by these keys is compared with the previous digit set up for the related storage columns. Any non-correspondence is indicated to the operator.

25 A further object of the invention is to provide an error correcting mechanism which will enable the release of the digital setup of the storage columns when an error is ascertained by the operator in the original digit set up or when the verifying arrangement in the machine detects a deviation in the original data set up during the keyboard operation for the verification of the original data. Obviously, when an error is located during the verifying operations, it is necessary that such storage columns be released so that they may be reset and again verified and a further object of the invention consists of a 30 selective arrangement which enables the storage columns in which the error has been located to be released without, however, effecting the digital setup of the storage columns pertaining to the preceding columns which have been determined to be correct by the verification of such columns.

35 A still further object of the invention is the provision of a digit storage arrangement which enables the representation of the digits according to a code so that while the digits 0 to 9 may be punched on the card, a lesser number of

relays may be utilized to set up such digital representations and a still further object of the invention in this connection is to provide a translator which will convert the combinational digit representation on the storage columns to the original digit representations 0-9 for the operation of corresponding punches in the punching machine.

In the instant device, the digit storage columns control a card punching machine of the successively actuated type and while the construction of the machine may be such that card punching operations are initiated after all of the storage columns have been verified, the preferred arrangement consists in the provision of an initiating mechanism for the card punch which will cause card punching operation to be effected under control of groups or sub-divisions of storage columns which have been verified and found to be correct in their digit representation. In this manner, the card punching operations closely follow the keyboard operations by the operator and as soon as a group of storage columns has been verified the punch operates immediately to punch the card under their control.

While the machine described up to this point is completely operative and admirably fulfills most of the requirements for card punching, it is further desirable that the card perforations be checked against the digital representation of the related storage columns.

A relatively important object of the invention is to provide a comparison of the card perforations with such storage columns and to provide the desirable overlap between card punching operations and checking operations for the previously punched columns. To this end, the original digit setup of the verified storage columns is retained and when the card previously perforated occupies a position in the punch whereby its perforations may be analyzed, a comparing mechanism is initiated which will compare the card perforation with the digit setup of the related storage column.

A still further object of the invention is to convert the digit representation of the card perforations according to the Hollerith system to a digit representation effected by the combinational code and which code corresponds to the code used for the digit representation of the storage columns. By provision of such means, the checking of the card punched according to the Hollerith system may be compared with the combinational digit setup of the controlling storage columns but if so desired the combinational setup of the storage columns may be converted to the digital representation according to the Hollerith system to obtain a direct comparison therewith.

A further object of the invention relates particularly to increasing the efficiency of machine operations and the desirable overlap between the punching operations and the card checking operations which will enable the latter to be initiated before punching operations are completed. The card checking operations are initiated after seven columns of the card have been punched but this is due to the relative column displacement of the card punches and analyzing brushes for the checking mechanism and by bringing such elements closer together, it will be seen that checking operations may be effected almost directly after the card column has been punched. However, the mode of operation in the present machine indicates that such overlapping opera-

tions ensue with an increase in the efficiency of machine operations.

Another object of the present invention is to release those storage columns which have been compared with the card perforations where indication of accuracy exists and the release of such storage columns will enable the operator to again set up the cleared-out storage columns to represent the digits of the next record. The sequence of operations of the verifying, card punching and check arrangements is such that in one point of the operation of the machine different operations may be effected. First, the verification of certain of the storage columns; the punching of the card under control of the verified storage columns; and further the checking of the perforated card columns with the related verified storage columns; and after the verification of one card, three operations may be concomitantly performed. That is, the punching of the card from the verified storage columns; the checking of the perforations of the card for comparison with the related verified storage columns; and further the setup by the operator of the storage columns which have been cleared out and found to be correct in their digit representation by comparison with the related perforated card columns.

As a further object of the invention, the machine includes further a series of signal lights which indicate the progress of the operator in the successive digit setup of the storage columns; either for the original digit set up or for the verification of the previous digit set up. It is preferable to provide a plurality of these signal lights; one signal light for each card field which consists of a plurality of card columns which receive the digit representation of related data.

A still further object of the invention in connection with the provision of signal lights is the incorporation of another signal light which will indicate visibly that the verifying of digit set up for any storage column has indicated a variance with the previous digit set up, and to make more clear this indication a single buzzer is also provided to audibly indicate the existence of an error. Preferably repetition of key strokes in an attempt to further verify successive storage columns will repeat this audible indication. A visible signal is also provided to indicate when a discrepancy is found between the digital representation of a perforated card column and the related storage column and while the machine continues with card checking operations of the machine in connection with the same card, the failure to eject the card which has been found to be perforated in error will be a further indication to the operator of the discrepancy, so that the incorrect card may be removed and keyboard operations can be repeated to produce a card which corresponds to the original data to be punched.

Other objects of the invention will be pointed out in the following description and claims and illustrated in the accompanying drawings, which disclose, by way of example, the principle of the invention and the best mode, which has been contemplated, of applying that principle.

In the drawings:

Figs. 1a to 1g when assembled in the order shown in Fig. 2 show the complete electrical wiring diagram of the combined verifying punching machine.

Fig. 2 outlines the manner in which the sheets 75 of the wiring diagram should be assembled.

Fig. 3 is a representation of part of a card perforated by the punching machine.

Fig. 4 is a central longitudinal sectional view of the preferred form of punching machine used in connection with the present invention, which form of punching machine is well known in the art. In addition to the conventional card punching mechanism the card analyzing device for checking the card perforations is also shown in this figure.

Fig. 5 is a chart showing the sequence of verifying, punching and checking operations clearly indicating the desirable overlap in these operations to increase the speed and efficiency of the machine.

Fig. 6 is a sectional view of the keyboard.

General description

The present arrangement consists of a keyboard, a relay storage unit and a punching machine, or card punch. The arrangement provides for punching a certain number of card columns with keyboard verifying and digital punching checking operations to insure accuracy in card punching.

A single storage unit is provided and to prevent any delay to the operator by punching operations from the storage unit it is desirable to provide an overlapped sequence of operating punch and storage units.

In general the operator first operates the keyboard to set up the desired data in the storage units. After the data has been set up, a second operation of the keyboard follows to verify the data set up in the storage units. If certain data previously set up is incorrect when the repeat keyboard operation varies from the first keyboard operation, a warning signal is given and by the provision of selective instrumentalities only a section of the storage units containing the erroneous setup need be wiped out, leaving intact the setup of the correct information. If the operator discerns an error in the first keyboard operation, all the storage units can be cleared of their data set up or, by the selective instrumentalities, certain sections of the data storage units may be cleared out upon an indication of an error.

Another novel feature of the invention is the possibility of causing punching operations to be effected under control of those storage units which have been found to be correct in their data set up. This overlap principle of operation enables the operator to verify the setting of storage units while the punch is operated to punch a card to represent the data set up on storage units previously verified and found to be correct. If so desired, the machine can be arranged so that it is possible to have the operator verify information on a storage unit while the punch is punching a column only one or two columns behind the operator. Simplification of the circuit is enabled by dividing the storage units in subdivisions generally corresponding to card field or parts of card fields so that the punch will not begin punching a card field until the operator has completely verified that subdivision of the storage units. The sub-divisions which are made for punching a card will be explained later.

As the punch punches the card it is desirable to check the punched information or data against the original setup in the storage units to determine whether correct punching operations have been effected. For this purpose the punch has incorporated an analyzing station preferably lo-

cated seven spaces or columns distant from the punches so that seven spaces after a column of a card has been punched the punched card column is read by the checking or analyzing station. A checking circuit is provided so that if the hole or holes analyzed do not agree with the setup of the storage unit for that column from which that card column was punched, an error indication is made and while further card checking operations may ensue card ejecting operations of the punch are suspended. After the punch has punched and checked one of the storage unit sub-divisions, that subdivision may be cleared in preparation for further setup operations. Thus, if the punch has been lagging behind the operator so that the operator is prepared to begin the setup of a new card before the punch has completed punching the previous card, it is possible for the operator to proceed with the setup to a point as far as the punch has completed the check without waiting for the punch to completely punch the card. In the normal speed attained by the operators in keyboard operations, the above sequence of events in overlapping relationship will eliminate any delay to the operators so that key operations may continue without interruption in spite of incidental operations effected in the punch such as card feeding and card ejection which are to be performed before a succeeding card is to be punched.

Keyboard

Mounted on the keyboard (Fig. 6) is a single series of ten digit keys 100 (Fig. 1b), marked 0-9 as well as an "Error" key 101 so designated, and a bar 102 known as "Manual bar." This bar is depressed to condition the machine for subsequent keyboard digit setup operations when the keyboard operations for verification have been completed.

Underlying the keys 100 is a bail 103 which operates to close a bail contact 104, such construction being well known. In starting, the first key depression causes a circuit to be closed from current supply line 105 through the bail contact 104, through relay contacts BR1 now closed, (Fig. 1a) line 106, through relay contacts TR1 now in the position shown, C2-11 now closed, to relay coil C1, to ground. Relay contacts C1-14 close to provide a stick circuit back to line 106 and relay C1 opens contacts C1-11 and closes contacts C1-12. The closure of the latter closes a circuit from line 106 through C1-12 contacts to relay coil TR to ground. Relay coil TR shifts its contacts TR1 but since contacts C1-11 are open the circuit to the C2 relay coil is opened and the latter is not energized during this first key depression, whereas relay coil TR is and remains energized by reason of its stick contacts TR4 which stick circuit extends through contacts TD1 now closed, relay contacts R2-1 now closed, the relay contacts MBR1 now closed, through wire 99, (Figs. 1a, b, c, d, e, f) to check release switch 98, (Fig. 1f) wire 97, back to line 105. Hence when the bail contacts open upon the release of the pressure on the depressed key, relay C1 de-energizes but relay TR remains operated. Upon the next key depression the circuit extends from line 106 through relay contacts TR1, relay contacts C1-11 now closed to relay coil C2 to ground, stick contacts C2-14 providing the stick circuit back to line 105. Relay coil C2 closes its contacts C2-12 to energize pickup coil P of grounded relay coil TD, which opens

its contacts TD1 to break the stick circuit of relay coil TR, which deenergizes. Relay coil TD closes contacts TD2 to provide a hold circuit to line 96 to insure that it is energized long enough to deenergize relay coil TR. The return of relay contacts TR1 to normal does not cause relay coil C1 to energize because of the opening of relay contacts C2-11. It is thus seen that on odd key depressions, relay coil C1 is energized while upon all even key depressions relay coil C2 is energized. As will be later explained relays C1 and C2 have their contacts in alternate columns of the storage units, with contacts of C1 in all odd columns and with contacts of C2 in all even columns. Thus, upon the first key depression, closure of contacts C1-1 (Fig. 1c) provides circuit to column 1 of the relay storage unit.

The contacts 107 (Fig. 1b) are closed by the respective keys 100 and a circuit is extended from line 105, through bail contacts 104, relay contacts BR2 now closed, (Fig. 1b) and line 108 to one side of all of these contacts. From the other side of these contacts there are respective wire connections 109 to relays KC1-KC9, one relay for each key, which relays are grounded so that a depression of a key will energize its KC relay and close respective KC4 contacts.

When the bail contact 104 closes a circuit is extended from line 105, by line 110 (Figs. 1a, 1b) to relay COM to ground. Relay COM transfers its contacts COM1 (Fig. 1a) and thus a circuit is completed from line 105, through contacts COM1 to relay coil CB to ground, and also from contacts COM3 to a wire 112 which is connected to all of the KC contacts. When TD relay (Fig. 1a) energizes its hold coil H will close its stick contacts TD2 (Fig. 1a) to provide a stick circuit by wire 96, through COM3 contacts back to line 105.

It will be noted that the KC1-KC9 contacts have wire connections to grounded relay coils K1-K4 through the normally closed relay contacts R3, 1-4 and the connections are such so as to energize relays K1 to K4 singly or in combinations according to the following code;

Key	Relay
1.....	K1
2.....	K2
3.....	K3
4.....	K4
5.....	K1, K2
6.....	K1, K3
7.....	K2, K3
8.....	K2, K4
9.....	K3, K4
0.....	None

Hence the KC1-1 to KC9-1 and 2 contacts energize the K1-K4 relays singly or in combination. The depression of the "0" key merely closes bail contacts 95 and bail contacts 104 to energize C1 or C2, depending upon whether the key depression is an odd or even numbered key depression.

It will be noted that to illustrate the present invention eleven storage units for storage columns 1-11 are shown, but the number may be varied. It will be observed then that in the depression of key "1" relay K1 closes its contacts in each storage unit, closing K1-1 contacts for column 1 to K1-11 contacts in column 11. The same is true for the other K2, K3, K4 relays so that for each key depression contacts will be closed in all of the eleven columns of the storage units upon each key depression.

It will be seen that for column 1 relays 11, 12, 13, and 14 are selected for energization by closure of respective contacts K1-1, K2-1, K3-1, and K4-1. Similar relays are provided for each column of the storage unit, relay coils 21-24 for column 2 being provided. The tens (and hundreds) digit is provided to indicate the column number and the units digit to indicate the relay number. Hence 52 indicates relay 2 in column 5; 114 represents relay 4 of column 11. Therefore, closure of K1 relay contacts in the storage units energizes relays 1-4 singly or in combination but only in the storage column selected for operation are such contacts effective for digit setup.

Upon the first key depression contacts C1-1 (Fig. 1c) are closed so that an energizing circuit for relays 1-4 of storage column 1 is provided from line 105, through supplemental bail contacts 95, (Fig. 1b), through CB2 contacts now closed, lower relay contacts R2A2 now closed, relay contacts C1-1 now closed, B2 contacts now closed to line 113, through relay contacts R3-7, the relay contacts P1-2 now closed, wire 115, to the particular K1-K4 contacts closed to the respective 11-14 relays to line 116, to ground.

Having been energized the relays 11-14 are held energized as follows: It will be noted that relays 1-4 in each unit are of the double type consisting of a pickup coil "P" and a hold coil "H" with the contacts adjacent marked "H" being the conventional stick or hold contacts which are closed when the pickup winding is energized. The stick circuit for relays 11-14 extends from ground, through the relay, its "H" contacts and wire 117, through D01-1 contacts to line 105.

It will be noted that from line 113 a circuit extends to grounded pickup relay coil A which closes its contacts A1 and which prepares column 2 of the storage circuit for entry of a storage impulse upon the second key depression, the impulse now being directed from K1-2, K4-2 contacts to energize relay coils 21-24. It is to be noted that the stick circuit line for these relays also extends by wire 117 back through contacts D01-1 and hence columns 1 and 2 are sectioned and constitute a sub-division.

Relay coil A closes its "H" stick contacts, the stick circuit extending back by line 118 (Fig. 1b) through relay contacts R2-9, and wire 120 to the line 105.

While relay contacts A1 are closed the digit impulse on the first key depression cannot be transmitted to relays 21-24 of the second column even though K1-2 to K4-2 contacts are closed because C2-1 contacts are open. However, on the second key depression relay coil C2 energizes to close contacts C2-1 and the second column will be set up, and in this case relay coil B energizes to open contacts B2 of the first storage unit to prevent setting up of column 1 storage unit on subsequent odd key depressions and closes contacts B1 in the column 3 of the storage unit, preparing it to receive the third digit set up.

Relay coil C energizes for the digit set up in column 3 opening contacts C2 to prevent a setup in column 2 and closing contacts C1 preparatory for a digit set up in column 4. In the same manner digit setup ensues for the eleven storage columns.

Relay coil B also closes its respective "H" stick contacts to connect the relay to the hold stick circuit line 118 and such column relays are held energized until released at a later time in ma-

chine operations, when relay coil R2 is deenergized.

The stick circuits for column relays of all columns are sub-divided as follows:

Storage columns	Relay coil	R2 contacts
1, 2	A, B	R2-9
3, 4, 5	C, D, E	R2-8
6, 7, 8, 9	F, G, H, I	R2-7
10, 11	J	R2-6

NOTE.—No relay coil is used for the last column, as it is unnecessary.

Similarly the stick circuits for the 1-4 relays of all columns are sub-divided as follows:

Storage columns	DO relays and contacts
1, 2	DO1-1 (Fig. 1c)
3, 4, 5	DO2-1 (Fig. 1d)
6, 7, 8, 9	DO3-1 (Fig. 1e)
10, 11	DO4-1 (Fig. 1e)

The impulse circuit for setting up the storage relays of column 11 will be described as it differs. Since column 11 is an odd numbered column, relay coil C1 is energized. A circuit is then completed upon making the key stroke for column 11 from line 105 (Fig. 1a) wire 124, relay contacts E11-2 now in the position shown, relay contacts MBR2 now closed, relay contacts COM2 now transferred, relay contacts C1-13 now closed, relay contacts J1 now closed, relay contacts R3A2 now in the position shown, relay contacts E11A1 now closed to the pickup relay coil of relay R1. The latter closes its contacts R1-3 to send an impulse to R2A relay coil. Now referring to Fig. 1b the storage impulse is directed from CB2 contacts now closed, through relay contacts R2A2 now transferred to wire 250 (Figs. 1b, c, d, e, in the order named) through the K1-11, K4-11 contacts to the 111-114 storage relays.

Error key operation

If at any time during the initial digit set up the operator discerns that an error has been made, the "Error" key (Fig. 1b) is depressed to close its contacts 119, extending a circuit from line 105 through contacts 119, line 121 (Fig. 1a) to relay E8 to ground. A circuit is also closed from line 121 through relay contacts R3A1, relay contacts P1-1, relay contacts E9-2 to relay coil E10 to ground.

The impulse to energize relay coil E8 is transmitted to the pickup coil of relay coil E8A. The latter opens to safety contacts E8A1 (Fig. 1f) to prevent an unwanted impulse from being directed upon an error key depression to relay coil SEA, to be later referred to. The relay coil E8A closes its hold contacts E8A4 (Fig. 1a) and the circuit then extends by wire 194 (Figs. 1a, b, c, d, e, f, g, in the order named) to contacts 227 in the punching machine now closed, contacts CL1 now closed, contacts 184 now closed, back to line 105. The stick circuit remains closed until contacts 221 open in a manner to be subsequently explained.

From Fig. 1f it will be noted that when column 1 is set up, relay contacts A3 close; when column 3 is set up, relay contacts C3 close; when column 6 is set up relay contacts F3 close and when column 10 is set up, relay contacts J3 close and hence as many as the above contacts are closed as storage columns are set up. Each of the above

A3, C3, F3, and J3 contacts are in circuit connection with grounded relays DO1, DO2, DO3, DO4 respectively, so that when relay contacts E10-1, 2, 3, 4 close, one or more DO relays will be energized. It will be noted that line 123 connects one side of the above relay contacts, the wire extending back in Figs. 1f, e, d, c, b, a, in the order named through contacts E10-9 (Fig. 1a) now closed, relay contacts E11-2 now closed in a manner to be explained, wire 124 to line 105. Relay coil E8 closes its contacts E8-1 extending the circuit connection by wire 122 to grounded relay coil E11, and also E11A in parallel therewith. Relay coil E11 transfers the related contacts E11-2 and as such contacts transfer, a circuit is closed from line 124 through E11-2 contacts to relay coil R2A to ground. The latter closes its contacts R2A3 to energize relay coil R2. The latter opens its contacts R2-9, 8, 7 and 6 (Fig. 1b), opening the stick circuit of the previously energized relays A-J.

Opening of the DO1-1, DO2-1, DO3-1, DO4-1 contacts opens the stick circuits for all of the energized storage relays in all of the columns receiving digit setup.

Hence, depression of the error key destroys all holding circuits of the storage units receiving digit setup and permits storage of digits to be made in the storage relay units beginning at the first column.

If the error key is depressed after an even key depression relay coil R2 opens its R2-1 contacts (Fig. 1b), thus breaking the previously described holding circuit for the previously energized relay coil TR, deenergizing the latter so that upon the next key depression for setting up column 1 an impulse will be directed to the C1 relay coil, which is essential in setting up column 1.

Initiation of verifying operations

Initiation of verifying operations is effected when a storage of a digit is effected in the last storage column; namely, the eleventh column and in the storage operation for the preceding

column 10 relay J is energized and held energized. Since column 11 is an odd numbered column, relay C1 is energized when a key stroke is effected for this column. As previously described, a circuit is then completed upon making the key stroke for column 11 from line 105 (Fig. 1a) wire 124, through relay contacts E11-2, relay contacts MBR2 now closed, relay contacts COM2 now shifted and closed because of the key stroke operation energizing relay COM as previously described, relay contacts C1-13 now closed, relay contacts J1 now closed, relay contacts R3A2 now in the position shown, relay contacts E11A1 now closed, to grounded pickup relay coil of relay R1.

Its grounded hold relay coil H is held energized through stick relay contacts R1-4, the stick circuit extending back through relay contacts MBR2, E11-2, wire 124 to line 105. When the key depressed for effecting the digit set up in storage column 11 is released, relay contacts COM2 return to normal and when the left set of relay contacts comes to normal a circuit is completed from line 105, wire 124, relay contacts E11-2, through relay contacts MBR2, the left set of relay contacts COM2 now closed, through relay contacts R1-1 now closed by energized relay R1, to grounded relay coil R3A and R3 in parallel therewith and both grounded. The hold circuit for relay coils R3, R3A is through the stick relay contacts R3A4, relay contacts

70 MBR2, relay contacts E11-2, wire 124 back to 75 MBR2, relay contacts E11-2, wire 124 back to

line 105. Relay contacts R3A2 transfer, preparing a circuit to relay R4 upon making the last key depression in verifying operations, which circuit will be later traced in detail when this operation is described.

Relay coil R3 is now energized and held energized and it will be seen that for each storage column there is a relay, such as relay AC for column 1, BC for column 2, etc., and in series with each relay AC, BC . . . C there is a related relay contact closed by relay R3. For storage column 1 there is a contact R3-7; for storage column 2 there is a contact R3-8, etc. to relay contacts R3-11 for storage column 11. Hence relay contacts R3-7 to R3-11 are all now closed.

Verifying operations

During verification the operator makes the same key strokes as in setting up the digits in the storage units to check the digit set up therein, and also to determine whether the data for the original data sheet has been correctly interpreted and the proper digit setup made.

Reference has been made to the circuits for effecting the successive energization of relays A-J and with relay contacts R3-7 to R3-11 now transferred, the energizing impulse not only passes to relay A (Fig. 1c) but also to one winding of a duo-coil relay AC (for storage column 1 by way of explanation). Therefore, A-J relays successively energize for column spacing during verification and one winding of duo-coil relays AC-KC also successively energize. The circuit for energizing the KC relay will be explained later. It will be noted that each relay AC-KC transfers its set of relay contacts 1-4, relay contacts AC1-4 (Fig. 1c) first closing, then relay contacts BC1-4 upon the second verifying key operation, and then successively to KC1-4 contacts (Fig. 1c).

It will be recalled that during key depressions for the initial digit set up relays K1 to K4 were selectively energized, but now that relay contacts R3-1-4 (Fig. 1b) are transferred the key impulses are transmitted to relay coils CK1 to CK4 and these are energized singly or in combination according to the adopted code. However, the other circuits previously described in connection with keyboard operations are made; that is, the sequential energization of relays C1, C2, and the energization of relays COM, CB. Each time relay coil CB energizes, a circuit is closed from line 105, through lower relay contacts CB1, (Fig. 1a) and by line 125 is extended to grounded relay coil CI. Relay coil CI closes contacts CI2 (Fig. 1b) providing a stick circuit for the energized CK1-CK4 relay through their "4" contacts, through CI2 contacts, wire 120 back to line 105.

An impulsive circuit for verification is extended from line 105, wire 120 (Fig. 1b) through relay contacts CI1 now closed, to lower relay contacts CP3-1 in the position shown and from such contacts the circuit extends through the upper relay contacts CP3-2, CP3-3, CP3-4, and CP3-5. All of these are now closed in this operation as shown and thence the circuit extends to the center blade of relay contacts CK1-1, CK2-1, CK3-1 or CK4-1 and to lines 130, 1, 2, 3 and 4 or 131, 1, 2, 3, 4, depending upon the transferred or normal position of the last mentioned contacts.

The manner of verifying operations can best be understood by reference to a specific digit set up, such as "1" in the 1 storage column. It will

be noted that relay coils 11, 12, 13 and 14 transfer their related contacts 11-1, 12-1, 13-1, 14-1 if such relays are energized and held energized, and for the digit setup "1," relay contacts 11-1 are closed. In the repeat digit setup of "1" contacts CK1-1 contacts are transferred, so that the verifying impulse is transmitted to line 130-1 but due to the transferred contacts 11-1, the circuit is open at this contact position. However, if the repeat key depression should be "2," contacts CK2-1 would be transferred and the verifying impulse will be transmitted to line 130-2 and since "1" was previously set up, contacts 12-1 are normal so that the circuit extends through such contacts, through AC3 contacts now closed, to line 132, (Figs. 1c, d, e, in the order named) through relay contacts CP3-8 to grounded relay coil PE. Relay coil PE closes its contacts PE3 (Fig. 1f) in a local lamp circuit, thus illuminating lamp 133 indicating an error in verification.

At the same time an impulse is sent to each of the lines 130, 1, 2, 3 and 4 to the normally closed side of the contacts 11-1, 2, 3 and 4, an impulse is sent to each of the lines 131, 1, 2, 3, and 4 to the normally open sides of the contacts 11-1, 2, 3 and 4. If any of these contacts are closed, indicating that a relay 11, 12, 13, 14 which does not correspond to any of the relays 11, 12, 13, 14 which was energized during the first digit set up, an error indication will result. It will be thus seen that an error test circuit is provided to indicate an error both where a relay has not been previously operated which should agree with the relay set up in the verification key operation, and where a relay was previously operated for which no relay is operated on the verification key operation.

The verification proceeds as above for each column, stepping from column to column in a manner similar to that employed in the initial setup.

Upon the very first indication of an error, relay PE energizes to close contacts PE3 (Fig. 1f) in a local circuit of flash lamp 133 and such relay is held energized by a stick circuit through stick relay contacts PE4, lower relay contacts E8-4 back to line 105. It will be recalled that the relay coil E8 for opening such contacts is energized by the depression of the error key and therefore the signal remains in visible position until the error key is operated.

From Figs. 1c and 1d, it will be observed that the verifying impulse circuits comprising the four lines 130 and the four lines 131 terminate at contacts controlled by relays 11 to 14 of storage column 1. These verifying impulse circuits could, of course, extend for verification of columns 8, 9, 10 and 11 but to prevent possible misoperations which will be more evident later on, it is preferable to provide a supplemental set of verifying impulse circuits for storage columns 8, 9, 10 and 11. From Fig. 1b, it will be evident that the verifying impulse relay contact CI1 is not only directed to CP3-1 contacts but by a wire 126, the impulse is extended through the lower relay contacts CP4-1, the impulse then extending through relay contacts CP4, 1-4 which are now in the position shown, thence to the center blade of relay contacts CK1-2, CK2-2, CK3-2, CK4-2 which contacts are also closed by the CK1-CK4 relays. The supplemental verifying feed impulse lines consist of a set of lines 126 similar to the impulse lines 130 and a set of impulse lines 127 which lines are similar to the lines 131 in respect to their connections to the con-

tacts controlled by the storage relays 1, 2, 3, 4 of columns 8, 9, 10 and 11.

It is clear, therefore, that after storage column 7 has been verified, the verifying impulses are directed by the lines 126 and 127 to verify the digit setup of columns 8, 9, 10 and 11. Of course, these verifying impulses are also sent to the lines 130 and 131 but they are ineffective because the AC to GC contacts remain open and it is only the impulses directed by the sets of lines 126 and 127 through the successively closed HC-KC contacts that are effective for verifying storage columns 8, 9, 10 and 11.

When an error has been located in any of the storage columns 8, 9, 10 and 11 by the verifying circuits operating in the manner previously described, an impulse is transmitted to the wire 128 (Figs. 1d, 1e) which passes through the contacts CP4-8, now in the position shown in Fig. 1e to the PE relay, which relay, upon its energization, as described, causes the illumination of the signal light 133, indicating an error in verification.

Audible indication of error in verification

Energization of relay coil PE closes relay contacts PE2 (Fig. 1a) so that while the key depressed in the verifying operation indicating an error is held down to energize relay CB, the transfer of CB1 contacts from the position shown in Fig. 1a transmits a circuit from line 105 through lower contacts CBI, along wire 125, through contacts PE2 to grounded "Buzzer," which gives the audible indication of an error in verification during the key stroke the error was ascertained. When the depressed key is released, a circuit is closed from line 105, through upper contacts CBI, wire 134, relay contacts PE1, to grounded relay BR. A hold circuit for the latter is completed from the hold relay coil through stick contacts BR6, relay contacts E8-2, wire 136, wire 99 (see Fig. 1f) switch 98, wire 97, back to line 105. Relay contacts BR3 (Fig. 1a) close so that for each succeeding key depression after an error in verification is ascertained a circuit is completed to "Buzzer" through contacts CB1, wire 125, relay contacts BR3, to "Buzzer."

Also to prevent further verifying operations upon succeeding key depressions, relay contacts BR1, (Fig. 1a) BR2, (Fig. 1b) are opened so that no circuit closed by the bail contacts 104 can be made by successive key strokes.

Selective clearance of storage units in particular sub-division error was ascertained

Reference was made previously to the provision of the error key and it will be recalled that operation of this key cleared all the storage units of their previous digit setup, as far as the digit entries were made. However, in verification, when an error is determined it is undesirable to clear out those storage units of their digit setup when such units have been found to be properly set up. Circuits are provided so that only that particular sub-division in which an error has been found releases the storage units of this sub-division. The number of sub-divisions provided can be varied and can even be sub-divided to provide for rectification of only a single column, but it is desirable, however, to sub-divide according to fields so that the related data of a field may be corrected in accordance with the original data sheet.

Therefore, the operator may then make an initial setup for those storage units found to be

incorrect, followed by repeat key depression for digit setting in those storage units for purposes of verification.

When the error key (Fig. 1b) is depressed following the determination of an error in the digit setup of a storage unit, the circuits previously described are closed to energize relays E8, E11, and E11A (Fig. 1a). Relay coils E8, E11, and E11A are energized by the circuits previously described, but since R3A is energized during the verifying operations the transfer of relay contacts R3A1 causes the impulse by wire 121 which energizes E8 to also be directed to grounded relay E9 but not to relay R10. The stick circuit for relay coil E9 is provided by stick contacts E9-10, wire 139, through relay contacts MBR1, wire 99, which it will be recalled extends back to line 105. Relay E8 transfers its contacts E8-2 to deenergize BR relay, and relay contacts E8-4 (Fig. 1e) open the stick circuit to PE relay, which opens its PE3 contacts (Fig. 1f) to extinguish lamp 133.

When relay contacts E8-1 close (Fig. 1a), a circuit is completed from line 121 through relay contacts E8-1, relay contacts R3A3 now closed, and thence through one or more contacts P4-1, P3-1, P2-1 which are at normal and thence to a certain one of the grounded relays E1, E2, E3 or E4.

Previous reference has been made to the successive energization of relays AC-KC as successive columns are verified. It will also be noted that the impulse which is directed through relay contacts R3-9 (Fig. 1c) to energize relay CC of the third column is also transmitted by a wire 142 through relay contacts DO1-2 now closed, to grounded relay coil P1. Therefore, relay coil P1 is energized when the third storage column has been verified. A stick circuit to hold relay P1 energized is through its hold contacts P1-4, wire 143, wire 117, through DO1-1 contacts now closed to line 105.

If an error is found in verifying columns 1 to 3 the error key is depressed, as described, and upon closure of contacts E8-1 (Fig. 1a), a test circuit is completed through these contacts, through relay contacts R3A3, relay contacts P4-1 to relay coil E4, and also through P3-1, P2-1 contacts now closed, to relay coils E1, E2, and E3. Columns 1-5 comprise the columns of data of one field so that upon locating an error in one of these columns the depression of the error key will result in the energization of relays E1, E2, E3 and E4 and the closing of relay contacts E1-3 and E2-3, E3-3 and E4-4 (Fig. 1f). The relay E8 being energized by the depression of the error key will transfer its E8-2 (Fig. 1a) contacts to cause a circuit to be completed from line 105, wire 97, (Fig. 1f) switch 98, wire 99 (Figs. 1f, e, d, c, b, a, in order named), wire 136, contacts E8-2 now transferred, wire 137 (Figs. 1a, b, c, d, e, f, in order named), through relay contacts E1-3, to grounded DO1 relay coil. Also a circuit is completed through E8-4 contacts now transferred (Fig. 1f), relay contacts E2-3, now closed, to grounded relay DO2. A circuit is also completed through relay contacts E11-3, now closed (Fig. 1f), through relay contacts E3-3 now closed, to grounded relay coil DO3. An impulse to energize relay DO4 is from line 105, through closed relay contacts E8-3 (Fig. 1f), relay contacts E4-3 now closed, to grounded relay coil DO4. All of these relays DO1, DO2, DO3, DO4 open their contacts DO1-1 (Fig. 1c), DO2-1 (Fig. 1d) DO3-1, DO4-1 (Fig. 1e), thereby clearing storage units of columns 1-11 inclusive.

The opening of contacts DO1—1 (Fig. 1c) breaks the stick circuit for relay coil P1, and opening of contacts DO1—2 prevents the pickup of relay coil P1.

It will be assumed that the field comprising columns 1—5 has been verified as correct but an error is located in the setup of columns 6—9 which comprise the next field. When the impulse for energizing relay coil FC (Fig. 1d) is transmitted thereto upon verifying the sixth column, an impulse is directed through relay contacts R3—12 by wire 147 to relay coil P2 to ground. A stick circuit for latter is provided by stick contacts P2—4, wire 148, (Figs. 1d, e) stick contacts DO4—2, (Fig. 1e) to line 105. Relay coil P2 opens its contacts P2—1 (Fig. 1a) when an error is located in columns 6, 7, 8 or 9 during the verification of these columns to prevent the test circuit impulse from energizing either E1 or E2 relays. However, the test circuit impulse initiated by the depression of the error key passes through relay contacts P4—1 to relay coil E4 and also through contacts P8—1 to grounded relay coil E3. The latter close their contacts E4—3 and E3—3 (Fig. 1f) so that upon closure of relay contacts E11—3 (Fig. 1f), a circuit is closed through relay contacts E11—3, E3—3 to relay coil DO3 and also through relay contacts E8—3 now closed, through E4—3 relay contacts to relay coil DO4. The latter opens their contacts DO3—1, DO4—1, thus clearing out storage columns 6—11 inclusive without, however, affecting the verified digit set up in columns 1—5.

Obviously, in the same manner when storage column 10 is verified, relay coil P3 (Fig. 1e) is energized and remains energized by a stick circuit like that described for relay coil P2. The opening of contacts P3—1 (Fig. 1a) enables only relay coil E4 to be energized by the test circuit so that only relay coil DO4 (Fig. 1f) is energized in this instance to clear out the storage columns 10 and 11.

For safety in operations, an alternative stick circuit to retain relays P2 and P3 energized is provided because when DO4 relay energizes on an error key operation, DO4—2 contacts (Fig. 1f) open the stick circuit. Therefore, from line 148 there is provided a connecting line 149 (Figs. 1d, 1c, 1b) extending as shown in Fig. 1b through relay contacts E9—9, now closed because relay coil E9 is energized upon a key operation, to wire 120 and back to line 105.

Summarizing, the depression of the error key during the verifying operation clears out the storage columns of the field in which an error is located and, as shown, preferably clears out the storage columns of unverified fields. However, those storage columns which have been verified as correct remain untouched and their digit setup remains.

Whenever relays E1, E2, E3, E4 are energized by the selective circuits previously described, their pickup and hold coils close their "4" stick contacts (Fig. 1a) thereby extending the stick circuit for the selectively energized relays through the stick contacts and thence via wire 150, wire 139, through relay contacts MBR1, wire 99, which it will be recalled extends in Fig. 1f back to the line 105. By the above holding circuits, the particular relays E1 through E4 which have been energized remain energized, such selective energization being according to the circumstances previously described.

Relay coils E1 through E3 open their respec-

tive contacts E1—2, E2—2, E3—2 (Fig. 1b), and such relay contacts are provided for the purpose of retaining the column relays A—I energized which pertain to the storage columns which have been verified as having been correct in their digit setup. Upon the depression of the error key, the relay R2 (Fig. 1a) energizes as previously described and opens its contacts R2—6, 7, 8, and 9, always opening, by relay contacts R2—6, the stick circuit for column relay J but tending to open all of the stick circuits for the column relays A—I for the first nine storage columns but, of course, the column relays pertaining to the storage columns which have been verified as correct which can only be column relays A—I should not be deenergized and the stick circuit for such column relays is maintained by the "2" contacts of the E1—E3 relays which remain deenergized.

For example, when an error is found in the digit set up for columns 1 to 5, relay coils E1, E2, E3 are energized and such relays open their "2" contacts shown in Fig. 1b. It will be recalled that upon the error key operation, relay coil R2 is energized, thereby opening the relay contacts R2—6, 7, 8, 9, thus opening the holding circuits for column relays A—J of storage columns 1—10. It will also be recalled that upon the error key operation the relay coil E9 is energized to close its contacts E9—3, 4, 5. In the assumed example, the "2" contacts controlled by the E1, E2, E3, relays are opened so that even though the relay contacts of relay coil E9 are now closed, all of the stick circuits for the column relays A—I are opened.

It will now be assumed that columns 1—5 which include column relays A—E have been verified as correct but an error is located in one of the columns 6, 7, 8 or 9 and according to the present embodiment this should result in the deenergization of the column relays F—J associated with storage columns 6—10. When an error is found in one of the columns 6—9, relay coil E3 is energized which will open its contacts E3—2, thereby opening the stick circuit for the column relays F—I. Relay contacts R2—6 open the stick circuit for column relay J. However, for columns 1 to 5, it will be noted that even though contacts R2—9 and R2—8 open, the stick circuit for column relays A and B will be maintained through relay contacts E1—2 now closed, thence through E9—3 contacts back to the line 120. The stick circuit for column relays C, D and E will be maintained through relay contacts E2—2 and relay contacts E9—4.

When an error is found in one of the columns 10 and 11, relay coil R2 will open its contacts R2—6, thereby opening the circuit for the column relay J of column 10, but relay contacts E1—2, E2—2, E3—2 will maintain the holding circuits for column relays A—I. It will also be remembered that there is no column relay provided for the last column 11 so that in the absence of such a column relay, it is unnecessary to effect its deenergization as is provided for in column 10.

Therefore, irrespective of the opening of the contacts controlled by the R2 relay tending to open all the holding circuits, the shunt "2" contacts controlled by the E1, E2, E3 relays will continue the holding circuits for the column relays pertaining to those columns which have been verified as correct, such holding circuits being maintained through the contacts closed by the E9 relay.

Means to insure proper alternating sequence of relays C1, C2 for recommencing storage of digits in cleared out storage columns

In order to insure that the alternating circuit for causing the energization of relays C1 and C2 will have the proper relation when the storage columns are reset after the verifying operation for such columns has determined an error, the special circuit shown in Fig. 1a has been provided. As explained, it is pointed out that if an error is found in storage columns 1 to 5, the clearing out of such storage columns and the subsequent digit set up requires that relay C1 be energized since the first stored column is to be column 1. On the other hand, when columns 6 to 9 are to be reset when an error has been determined in setting up one of these columns, it is necessary that the setting up of the storage columns be controlled by the energization of the C2 relay since the first column set up is column 6 which is an even numbered column. The same condition obtains with columns 10 and 11 as is found for columns 6 to 9, that is, relay C2 must be energized because in the restorage of the digits for storage columns 10 and 11, the first column is column 10 which is an even numbered column.

Contacts E1-1, E2-1, E3-1 and E4-1 are interconnected and wired as shown in Fig. 1a and such contacts are transferred from their normal position in accordance with the energization of the relays E1 through E4.

When an error has been found in any of the columns 1 to 5, the relays E1, E2, E3 and E4 are all energized so that all of their "1" contacts are transferred. Upon the depression of the error key, relay coil R2 is energized as previously described, causing the transfer of contacts R2-2, thereby extending the circuit from the line 105, wire 145, through left hand relay contacts R2-2, thence serially through the transferred contacts E4-1, E3-1, E2-1 and E1-1 to the pickup coil of the relay TD, thereby energizing relay coil TD and causing the opening of the stick contacts TD1. The opening of such contacts will result in the deenergizing of the stick circuit for the TR relay and in view of the deenergization of the TR relay contacts TR1 will restore to the normal position shown. This is the normal position of the contacts and the controlling circuit when the first digit setup is made and therefore, upon the first digit set up following the depression of the error key, relay coil C1 will be energized and the digit set up will be made in storage column 1.

When an error is located in any of the columns 6 to 9, the assurance that the first storage digit set up following depression of the error key is effected in column 6 which is an even numbered column is made by the wiring of the "1" relay contacts controlled by the E relays. When an error is located in any of the columns 6 to 9, inclusive, relay coils E4 and E3 will be energized, thereby transferring their "1" contacts so that the impulse circuit from transferred relay contacts R2-2 will pass through transferred contacts E4-1 and E3-1, thence to the relay coil TR. The latter now being energized will transfer its contacts TR1 so that the relay coil C2 will be energized upon the next key depression which is for storage column 6; an even numbered column.

A similar circuit is effected to cause the energization of the TR relay coil upon the first key

depression following the depression of the error key, it being noted that for columns 10 and 11 relay coil E4 is energized, thereby transferring its contacts E4-1. The impulse will pass from transferred relay contacts R2-2, thence through transferred contacts E4-1, thence through the upper relay contacts E3-1 to the relay coil TR. Hence, the first digit set up will be made for storage column 10.

- 10 It will be recalled that the stick circuit for relay coil TR is through the stick contacts TR4, through contacts TD1 and thence through relay contacts R2-1 and relay contacts MBR1, wire 99, back to line 105. It will also be remembered 15 that upon the depression of the error key, relay coil R is energized which will open its contacts R2-1 and since this will result in the opening of the stick circuit, safety contacts E9-1 are provided and such contacts shunt relay contacts 20 R2-1 and insure that the stick circuit will be maintained through relay contacts R2-1 upon the completion of the depression of the error key.

Manual bar operation

- 25 As previously intimated the machine includes a manually operated bar which is known herein as a "manual bar" and which causes certain operations to be performed upon completion of the 30 last key stroke of the verifying operations. It will be well at this time to understand the various circuits which are effected by the depression of the manual bar. When the next to the last storage column is verified, relay coil J is energized and upon verifying the eleventh storage column relay coil C1 is energized because this storage column is odd-numbered. When relay contacts C1-13 (Fig. 1a) are closed by relay coil C1 and with relay contacts J1 already closed, 35 a circuit is completed from line 105, via wire 124, through relay contacts E11-2 now in normal position, through relay contacts MBR2 now closed, thence through transferred relay contacts COM2 which close upon the depression of 40 the key for verifying the last storage column, the circuit then extending through relay contacts C1-13, relay contacts J1, thence through the left relay contacts R3A2 which are now closed, to grounded relay coil R4; resulting in the energization of this relay coil and relay coil R4A 45 in parallel therewith. Relay contacts R3A2 are transferred at this time because the machine operation is a verifying operation. Relay contacts R4A4 are stick contacts, thereby providing 50 a stick circuit through these contacts and via wire 165, (Figs. 1a, b, c, d, e, in the order named) through left relay contacts E11-4 now in the position shown, thence through relay contacts DO4-2, back to the line 105. Hence, relays 4 and 4A are energized by the last key stroke of 55 the verifying operation and relay coil 4A, instead of deenergizing upon release of the last key struck, holds until the end of the card punching operation.
- 60 For energizing KC relay of storage column 11, a special circuit is provided and since relay coil R4 is energized during the last verifying key stroke, relay contacts R4-3 (Fig. 1b) are closed so that the impulse circuit is from line 135, 65 through bail contacts 95, (Fig. 1b), contacts CB2, relay contacts R4-3 to wire 250 (Figs. 1c, d, e, in the order named) through relay contacts R3-11 now closed, to grounded KC relay coil.
- 70 A warning signal is given to the operator in 75

the event that the manual bar is depressed before verifying the last storage column. Upon the depression of the manual bar a circuit is closed from the line 105 and via wire 166 (Fig. 1a) the circuit is extended to the contacts which are closed upon the depression of the motor bar 102. The circuit then extends from such contacts via wire 167 to relay contacts R4A1 (Fig. 1a). If the last storage column, namely column 11, has not been verified, relay coil R4A will not be energized and therefore contacts R4A1 will be in the position shown so that the circuit will extend through the left hand contacts and via wire 168 (Figs. 1a, b, c, d, e, f, in the order named) to grounded relay coil PE. Reference has been previously made to this relay and it will be recalled that it was described as having the function of lighting an error signal lamp 133, and also to complete a circuit to the "Buzzer" shown in Fig. 1a. In the same manner and by the same circuits both of these signals will be given in the event that the operator depresses the manual bar before the last column has been verified.

If the last storage column has been verified, relay contacts R4A1 (Fig. 1a) will have been transferred so that the circuit will extend from the wire 167, then through the right hand contacts R4A1 to a wire 169, the circuit then extending through relay contacts BR4 now closed and to grounded relay coil MBR. The latter closes its contacts MBR3 so that the circuit is extended through such contacts to relay coil R2A. The latter closes its contacts R2A3 to energize relay R2. The opening of contacts R2, 6, 7, 8 and 9 by R2 relay (Fig. 1b) will break the holding circuits of the column relays A through J in the manner previously described.

The opening of the relay contacts MBR1 shown in Fig. 1a breaks the holding circuit for the relay coil TR so that if this relay had been left in its energized condition by the last key stroke, the following storage digit setup operations could take place with relay coil C1 operating first as is necessary for correct sequencing. The transfer of relay contacts MBR1 also break the stick circuit for relay coil E9 and also the stick circuit for all of the relay coils E1, E2, E3 and E4 which may have been previously energized. The closure of the right hand relay contacts extends a circuit from the line 105 by wire 99 through the right hand relay contacts MBR1, thence via wire 172 (Figs. 1a, b, c, d, e, in the order named) thence via wire 172 which extends to the grounded relay coil P4, thereby causing the energization of this relay coil. The stick circuit provided for this coil is through contacts P4-4 to the aforementioned holding circuit line 148.

Punching mechanism

As previously intimated, a punching mechanism is provided whereby a card may be punched to represent the data which is stored up in the storage relay devices comprising, in the present machine, eleven columns. The card which is to be punched is shown in Fig. 3 wherein it will be noted that the first nine columns have been prepunched to represent common data for a series of cards so that the punching of the digit set up on the storage relay devices commences from column 10 and continues successively through column 20 of this card. It will be noted, therefore, that columns 1 to 11 of the storage devices control punching of columns 10 to 20 of the card and in the ref-

erence "card columns" it will be understood that these refer to the columns of the card. While the punching operation could be initiated when the digit setup of all the storage columns have been verified, saving in time in machine operations will be made by having card punching operations automatically ensue upon the completion of verification of the digit setup of some of the storage relays. For this reason the circuits 5 are arranged so that upon completion of the verification of one sub-division, punching is automatically effected under control of the storage relays for that sub-division and while punching operations are being effected, the operator goes 10 through the repeat key depressions to determine whether the next subdivision of relay storage devices is correct in its digit setup. When this subdivision has been verified and it has been determined that its digit setup is correct the 15 punching operation is then initiated to punch the data pertaining to the next sub-division. This mode of operation continues until all of the card columns have been punched out under control of the storage relays. Tabulated, the punching operations are effected as follows:

Upon completion of verification of column	Relay coil energized	Storage columns read out	Card columns punched
3.....	P1	1, 2	10, 11
6.....	P2	3, 4, 5	12, 13, 14
10.....	P3	6, 7, 8, 9	15, 16, 17, 18
11.....	P4	10, 11	19, 20

35 Any suitable type of punching mechanism may be provided for digit recording and other forms of recording machines may be utilized but preferably a punching machine of the type shown in the patent to F. Lee et al., 1,976,618 is utilized. 40 The punching machine is generally shown in Fig. 4 but not in full detail as in this patent, to which recourse may be had for full information. Later on a general operation of the punching machine will be given in connection with the wiring diagram. At the present, it is only necessary to understand that the machine includes a series of punches which punch cards according to the Hollerith system and the punching operations are effected successively by the provision of a 45 card carriage which escapes column by column as the successive punching operations ensue. As is also well known, in the form of punching machine referred to a skipping mechanism is provided where certain card columns of the card 50 may be skipped past the card punches without punching operations being effected for such card columns. In the present machine all of the cards are punched in the first nine columns with data which is common to a series of cards and by 55 means of this well known skipping mechanism the card carriage, when it is returned to column 1, automatically skips to column 10, in which position the card carriage is in when the operator has completely verified the digit set up in storage columns 1 and 2. Hence, the punching machine is picked up for punching operations upon 60 completion of verification in columns 1 and 2 so as to punch card columns 10 and 11, this being one of the sub-divisions previously referred to.

65 It should also be understood that the punching machine shown in this patent punches cards according to the Hollerith system, that is, a perforation is placed at a differential location to 70 represent the digits set up in the storage columns.

For this reason, the combinational setting of the relays must be translated to a single digit representation. Such forms of translators are well known and briefly for storage column 1 the energized relays 11, 12, 13 and 14 (top of Fig. 1c) transfer their respective "2, 3, or 4" contacts and such contacts are closed in combination in accordance with the code, and being interconnected in combination select one of a series of digit lines 180 (Fig. 1c to Fig. 1g) which are marked 0 to 9, inclusive. The digit lines 180 are connected to grounded punch magnets 182 (Fig. 1g and Fig. 4) and such punch selecting magnets correspond to the punch selecting magnets 60 of the aforementioned Patent No. 1,976,618. Therefore, according to the particular contacts of the translator which are open and closed, one of the digit lines will be selected so as to select for energization the desired one of the punch selecting magnets 182. It should also be noted that in the event that none of the digits 1 to 9 are stored in a particular storage column all the relay contacts of the translator relating to that storage column will be at normal position so that normally the "0" punch selecting magnet 182 will be selected for operation. Taking for example storage column 1 (Fig. 1c) it will be noted that due to the normal closure of contacts 11-2, 12-2, 13-2 and 14-2 in the translator for column 11, the readout line 183 for this column will have a normal connection through such relay contacts to the "0" digit line 180, thereby selecting the "0" punch selecting magnet 182 for energization. If other relay contacts in this translator are closed, another circuit will be closed from the line 183 through such contacts so as to select the appropriate digit line 180. The line 183 for the first storage column is the readout line for the translator of storage column 1; that is to say, when this circuit is closed, the initiation of the punching machine will be effected so as to punch card column 10 which is the starting card column position of the card carriage. Punching in card column 10 will be effected when columns 1 and 2 have been verified and relay coil P1 energized when storage column 3 has been verified.

Initiation of punching operations and the successive punching operations of the punching machine referred to are effected under control of a device known as a "column readout device" which is well known in the form of punching machine described and is fully shown in Fig. 3 of the patent to G. F. Daly, et al. No. 2,016,706 and reference may be had thereto for further details.

Referring to Fig. 1g, it will be noted that from the line 105 there is a wire connection to contacts 184, the circuit then extending through card lever relay control contacts CL1 now closed to contacts 185, thence to a line 187. Contacts 184 correspond to the contacts designated 136 in Patent No. 1,976,618 and are operated similarly and have corresponding functions in the punching machine shown herein. Contacts 185 are similar in operation and function to contacts designated 128 in Patent No. 1,976,618. Both of the contacts 184 and 185 are normally closed. The wire connection 187 extends to the movable brush 188 (Fig. 1f) of the column readout device and the brush 188 consists of two sets of four brush strands.

In the present case the column readout is of a duplex construction so that both brushes will contact with corresponding column contacts 189 and 191 and then as the card carriage steps column by column the two brushes will make successive contact with the corresponding contact

points 189 and 191 of the two sets. Some of the contact points are not wired although they are shown in Fig. 1f but those which are wired make circuit connections which will be subsequently explained.

When the key stroke for verification of column 3 is made relay P1 (Fig. 1c) is energized and this results in the closure of relay contacts P1-3 (Fig. 1c). The previous skipping of the card carriage to column 10 now provides a circuit from line 105 through contacts 184 now closed, thence through relay contacts CL1 closed in a manner to be subsequently explained, thence through contacts 185, wire 187, to the brush 188 (Fig. 1f) contacting the contact point 189 at the tenth column position, thence to grounded relay coil B2 and the latter energizes and closes its contacts B2-1 (Fig. 1c). It will be understood that at any column position of the carriage the brushes 188 complete a circuit from line 105 to the contact point 189 or 191 it engages. In the circuit now being considered for punching card column 10, it will be seen that from wire 183 (Fig. 1c) connected to the translator of storage column 1 contacts B2-1 and P1-3 are in series connection therewith and by wire 194 (Figs. 1c, d, e, f, g, in the order named), the circuit extends through contacts 221 now closed, CL1 contacts controlled by the card lever control relay CL now energized to close its contacts in a manner to be subsequently explained, thence through contacts 184 now closed to line 105. Contacts 227 are operated similar to contacts 185 and therefore are supplemental contacts operated like contacts 128 in Patent No. 1,976,618. In accordance with the setting of a translator, there is a circuit connection to the selected punch selecting magnet 182. The punch now perforates column 10 and the card carriage escapes in the usual manner to column 11. At column 11 a circuit is completed from the translator of storage column 2 by a wire 195 (Figs. 1c, d, e and f) connected as shown in Fig. 1f to the contact point 189 at the eleventh card column position.

Obviously, when storage columns 1 and 2 have been verified as correct, the key stroke for verification of column 3 causes the energization of relay coil P1 and initiates punching of columns 10 and 11 under control of storage columns 1 and 2 as is clearly outlined in Fig. 5. While the card carriage escapes to column 12 after punching card column 11 the punching of card columns 12, 13 and 14 does not take place unless the related storage columns 3, 4 and 5 have been verified and a key stroke is made to verify column 6 which causes the energization of the relay coil P2 (Fig. 1d) to close its contacts P2-3 (Fig. 1c). This operation is also outlined in Fig. 5.

When contacts P2-3 close the translator for storage column 3 (Fig. 1c) is then connected to the line 105 through contacts P2-3, wire 196 (Figs. 1c, d, e, and f) which wire is shown in Fig. 1f as connected to the column contact point 189 at column 12. The punch then punches card column 12 and the card carriage escapes to column 13. The translator of storage column 4 for punching card column 13 is connected to the line 105 by a wire 197 (Figs. 1c, d, e and f) connected as shown in Fig. 1f to the column contact 189 at the thirteenth card column position. Thereafter the card carriage escapes to card column 14 and storage column 5 for punching card column 14 is connected to the line 105 by a wire 198 (Figs. 1d, e, and f) which is shown in Fig. 1f as connected to the contact point 189 at the fourteenth card column position. The card carriage then

escapes to card column 15 and from contact point 189 at column 15 there is a wire connection to relay coil B4 which, upon the escapement of the card carriage to column 15, causes the energization of relay coil B4 and the latter closes its contacts B4-1 (Fig. 1d). It will be recalled that the wire 194 extends back through the circuit previously outlined to line 105 but it will be seen that wire 200 (Fig. 1d) connected to the wire 194 extends the circuit through relay contacts B4-1 now closed but the circuit connection to the translator associated with storage column 6 is open at relay contacts P3-3 and until such contacts are closed by the energization of the relay coil P3 when storage column 10 has been verified, storage column 6 cannot be utilized as a control for card punching operations for punching card column 15 as is outlined in Fig. 5. When the key stroke is made to verify storage column 10 relay coil P3 (Fig. 1e) is energized and contacts P3-3 (Fig. 1e) close so that the translator associated with storage column 6 is now effective for punching card column 15. As outlined in Fig. 5, punching of card columns 15, 16, 17 and 18 then ensue, taking place under control of the translators associated with storage columns 6, 7, 8 and 9.

At card column 16, relay coil B5 (Fig. 1f) is energized to close contacts B5-1 (Fig. 1d) so that the closing of the latter completes a circuit from the translator associated with storage column 7 through such contacts to the wire 202 thence to the wire 194 which feeds back to the line 105 by the circuit previously described. After punching card column 16 the carriage escapes to column 17.

For punching card column 17 it will be noted by reference to Fig. 1f that when the brush 188 contacts the contact point 191 at card column 17 a circuit is closed to energize relay coil CP3. When brush 188 engages the contact point 189 at card column 17 a circuit is closed by wire 231 (Figs. 1f, e, d, c, in order named) to one winding of relay coil AC. Contacts AC6 (Fig. 1d) are now closed by the energization of column relay AC associated with storage column 1. Relay coil CP3 closes its contacts CP3-13 (Fig. 1d) so that a circuit from the translator associated with storage column 8 is closed through relay contacts AC6, thence through contacts CP13, relay contacts E4-2 now closed thence to the line 194 which, it will be recalled, extends back to the line 105 through the circuit previously traced.

When card column 17 has been punched, the card carriage escapes to column 18 and by reference to Fig. 1f it will be seen that at this card column position relay coil B7 is energized which closes its contacts B7-1 (Fig. 1e), thereby connecting the translator associated with storage column 9 through contacts B7-1 to the line 194 which extends the circuit back to the line 105. The punching of card column 18 causes the card carriage to escape to card column position 19 and the punching of card columns 19 and 20 then ensues but punching of this field of the card comprising such card columns is initiated only when the manual bar 102 is depressed to cause the energization of relay coil P4. This is outlined in Fig. 5 and it will be recalled that after verifying storage column 11, the manual bar is depressed to cause the energization of relay coil P4. The closure of relay contacts F4-2 closes a circuit for the translator associated with storage column 10 through such contacts, thence by wire 207 (Figs. 1e and f), the circuit is extended to the column contact point 191 at the nineteenth

card column position. The card carriage escapes to column 20 after punching card column 19 and by a wire connection 208 (Fig. 1e) from the translator associated with storage column 11 the circuit for this translator is closed by wire 203, which as shown in Fig. 1f is connected to the column contact 191 at the twentieth card column position. The card carriage then escapes to card column 21 at which card column position as shown in Fig. 5 there is an automatic spacing of the card carriage column by column to column 28.

Observing Fig. 5 it will be noted that card columns 10 to 20 are punched in sub-divisions (10 and 11), (12, 13 and 14), (15, 16, 17 and 18) and (19 and 20). Punching operations are initiated for each sub-division when the storage columns for controlling each sub-division of punching have been verified as correct and when verification of the first storage column of the next sub-division commences. The control of relays P1, P2, P3 and P4 for initiating punching of sub-divisions of card columns is also made clear in the schematic outline of Fig. 5.

In actual operation the punching operations closely follow the manual verifying operation and just as soon as storage columns of a sub-division have been verified, the punch operates to punch related card columns of such sub-division. Great saving in time is effected by such overlapping operations. At this time it may be well to consider the actual structure of the punching machine shown in Fig. 4.

Card punching machine

The card punching machine used in connection with the present invention is of the type shown in the patent to Fred Lee and George Daly, No. 1,976,618, dated October 9, 1934, and only so much of the operation thereof will be explained as is necessary for an understanding of its operation in connection with the present invention.

In general, the punching machine contains a feed magazine 53 (Fig. 4) from which the cards are fed singly from the bottom of the magazine as is well known by a picker which feeds the cards to a position under the punches 55 and in the present machine, the carriage escapes in the usual manner to present the tenth column of the card to the punches preparatory to receiving the perforations effected by the first punching operation. From this position, the card is engaged at its rear edge by a pusher 54 mounted upon an escapement rack 56 which, for each operation of the punches, permits the advance of the card step by step. The series of magnets 182 is adapted to select the punches 55 for actuation in the following manner. Associated with each magnet 55 is a pivoted armature 57 whose free end is connected to a rod 58 which, through a bell crank 59, moves an interposer bar 60 to the left in Fig. 4 where it cooperates with a punch bar or plate 61. The forward movement of the interposer bar 60 is adapted to rock a bail 62 pivoted on a rod 63 and which bail is connected to a spring pressed depending link 64 whose lower free end is adapted to engage and close contacts 65. This, as shown in Fig. 1g, closes a circuit from the line 105 through contacts 65, through the magnet 66 to the ground. The energization of the magnet 66 will then attract its armature 67 (Fig. 4) and through a link and bell crank connection 52 shown in the aforementioned patent will draw downwardly on the piv-

oted punch bar or plate 61 to force the selected interposer against the associated punch, thus perforating the card.

The selection of the magnets 182 which are punch selectors for effecting the punching operations is under control of the translators pertaining to the related storage columns and such translators are read out column by column to effect successive card punching operations.

As is fully shown in the patent to Lee et al., No. 1,976,618 when the armature 67 reaches the limit of its movement to the right, the link 64 will be moved by a projection 52a to become disengaged from one of the spring blades of contacts 65 to permit such contacts to open, thereby deenergizing the magnet 66 which will then release its armature, allowing a spring 68 to rock the plate 61 upwardly and permit the selected interposer 60 to rise and thereafter be restored to normal position by a spring 69.

Escapement mechanism

The escapement mechanism is not shown herein since it is fully shown and described in the Patents Nos. 1,976,618 and 1,426,223. It will suffice to say that when an interposer 60 is depressed it will rock a ball 70 attached to a shaft 71 and the rocking of this shaft will actuate the escapement mechanism to space the card carriage a single column.

Column selector

The column selector for the punching machine illustrated herein is also well known and is shown in the patent to G. F. Daly et al., No. 2,016,706, dated October 8, 1935. As shown in Fig. 4 as well as in Fig. 1g it consists of a movable contact brush 188 carried by the punch carriage engageable with contact points 189, and contact points 191, respectively, some of which are connected so as to cause certain functions to be performed when the carriage is at certain column positions, as previously described, and further functions in a manner to be subsequently explained.

Incidental operations in punch

These operations consist of the closing of contacts 76 (Fig. 1g) which are closed in the last column position of the card carriage and which contacts are the same as contacts 191 in the Patent No. 1,976,618 and closed in the manner described in this patent. The closure of contacts 76 energizes the card eject control magnet 77, which corresponds to magnet 199 of the aforementioned patent.

As the card is ejected, contacts 18 correspond to contacts 201 of the aforementioned patent will complete a circuit to grounded magnet 79, which corresponds to magnet 175 of the Lee et al. Patent No. 1,976,618.

Magnet 79 (Fig. 4) will attract its armature 80, and the arm 81 thereof will bear upon an insulating block to open contacts 184 and close contacts 190 precisely as in the last mentioned patent. Contacts 190 now being closed close a circuit to the motor 157 which is the same motor in the Patent 1,976,618 and similarly designated. At the same time, as is well known and explained in Patent No. 1,976,618, arm 81 effects the engagement of the clutch between this motor and the moving mechanism for the card carriage, which automatically feeds a blank card thereon for the next card punching operations, and returns the carriage to an initial starting position.

These incidental operations are explained herein mostly by reference to the wiring connections of the elements involved to effect these incidental operations. These operations, in the 5 form of punching machine selected as an embodiment, are very well known and recourse to the patents referred to for such will give further details of construction and operation.

10 *Card column spacing without punching operations*

As will be later evident it is necessary to effect successive column spacings of the punch card carriage without, however, causing punching operations. This mode of operation is well known and in general consists of an interposer 82 (Fig. 4) which normally underlies the punch plate 61 so that when punch magnet 66 is energized, the rocking of the punch plate 61 will, through this interposer, rock escapement bail 70 to space the card carriage one column. This interposer 82 has either a cutout portion 83 or is so positioned outside of the field of punches 55 that it cannot operate any of the punches 55. Thus, successive energization of the punch magnet 66 will column space the card carriage, and as will be presently described such spacing operations are effected in order to "check" the perforations, or more specifically comparing the perforations with the digit set up in the storage relays to determine or verify the correctness of card perforating operations. From the schematic diagram it will be noted that punching and 25 checking operations overlap in order to save operator time. Further, when perforating is found to be correct the storage relay setup is released, enabling the operator to use them for the next digit set up in such storage relays.

40 *Checking of perforations made on card*

The checking operations now to be described comprise a comparison of the digital value of the card perforations with the digital value setup in 45 the storage columns and is initiated when the punch card carriage has spaced to column 17, as shown in the sequence diagram of Fig. 5. Succeeding checking operations are effected as the card carriage spaces step by step to column 28 50 position, after which the usual skipping mechanism operates to skip the card carriage to the last column position, with card ejection being subsequently performed. Part of checking operations i. e. for columns 10, 11, 12 and 13 take 55 place concomitantly with punching operations for columns 17, 18, 19 and 20, as will be apparent from the sequence chart. Further, when checking of the first storage columns and the related punched card columns has indicated accuracy, 60 the sub-divisions of the storage columns checked are released so that even while punching and checking operations are being performed, key operations by the operator may be performed to again set up the released storage relays according to the next data.

The comparison of punched card columns with the storage columns involves the same digit comparing circuits described for verifying operations except that since the digital setup on the storage 70 relays is according to a combinational code, and the digital recording on the card is according to the Hollerith system, that is, one differentially located hole represents each digit, a conversion is made to convert the punched hole digit representation to a combinational representation,

using the same code as for the storage relay digit representation.

The analyzing brushes 225 (Fig. 4) for analyzing the punched card columns are located beneath the card carriage and when elevated engage a contact roller 226 located above the card carriage through the card perforations. The contact roller and sensing brushes 225 are spaced from the punches so that the holes made by the punches pass the roller and brushes after a 7-column interval, i. e., when card column 1 is under the analyzing brushes, column 8 is under the punches 55. The roller 226 is shown in Fig. 1g as being co-extensive with the 9 digit receiving rows of the card. Separate wipers 151 (Fig. 4) supply current to the brushes 225. Beneath the contact roller 226 is the row of nine brushes 225 which are carried by a block 153 of insulating material. Mounted at each side of the insulating block 153 is a pair of guide plates 152, each provided with a cam slot 154 receiving a pin 155 carried by the insulating block. Pivoted upon each plate 152 at 156 is a plate 158 pivoted at 159 to the block 153. Obviously, by rocking the plates 158 about their pivotal points 156, the pivotal connection 159 to the block 153 will force the latter to the right as viewed in Fig. 4 and also upwardly, guided by the coaction of pins 155 in the inclined slots 154, thereby bringing the brushes 225 slightly to the right as well as upwardly so as to make contact through the perforations of the card with the contact roller 226. For rocking the plates 158 to effect this operation there is provided a magnet 160 which attracts its armature 161 so that extensions 162 thereof will rock the respective plate 158.

The magnet 160 is also shown in Fig. 1g and the circuit for effecting the energization of this magnet to render the card analyzing device effective will now be described.

It is common to provide a card lever which is mounted on the punch bed of the punching machine and when a card has been fed from the supply hopper 53 to such position, this card lever 163 will be operated to close contacts 164, thereby closing a circuit from the line 105 through contacts 184, thence through contacts 164 to grounded CL relay coil shown in Fig. 1f. The latter closes its contacts CL2, thereby extending the circuit from such contacts by a wire 173 through contacts 169 now closed (which correspond to contacts 226 in Patent No. 1,772,186 and operated in the same way), and contacts 170 when the card has been fed to the analyzing device sufficiently to operate a card lever to close such contacts as will be subsequently explained, thence to the grounded magnet 160. Contacts 170 are also shown in Fig. 4. When the leading edge of the card passes by the punches 55 it will engage and rock a card lever 171 to close the contacts 170. Therefore, dependent upon a card located on the punch bed of the punching machine and in position for having its card perforations analyzed, magnet 160 is energized to thereby position the brushes 225 for analyzing the card perforations.

When the card carriage escapes to the first column position 17 for checking, contacts 185 (Fig. 1g) close, as they do for each card column position. These contacts, as previously stated, are similar to contacts 128 of the machine shown in Patent No. 1,976,618 and are operated the same way. A circuit is now closed from line 105, through contacts 184, through CL1 con-

tacts, through contacts 185, to contact roll 226 and in accordance with the card perforations selectively energize one or more of the grounded relays CR1—CR9. Relays CR1—CR4 are energized singly to represent digits 1—4 but digital representations 5—9 are required to be converted to a combinational representation.

When the card carriage reaches column 17, the seventeenth contact point of the series 191 is engaged by the brush 188, completing a circuit from line 105 through such brush and contact point to grounded relay coil CP3, (Fig. 1f). The latter closes its stick contacts CP3—16, the stick circuit extending back to line 105 through relay contacts DO4—2, (Fig. 1e). Relay coil CP3A in a parallel with CP3 energizes concurrently and shifts its contacts CP3A, 1, 2, 3, 15 (Fig. 1g).

For the digits 1—4 there is no conversion and circuits may be set to energize relays CR1 to CR4 as follows:

Hole	Relay
1	CR1
2	CR2
3	CR3
4	CR4

For digits 5—9 there is a conversion which is enumerated as follows:

Hole	Relay energized	Contacts closed	Circuit through relay contacts	Relays energized
35				
5	CR5	CR5-1 CR5-2	CP3A-3 CP3A-2	CR1 CR2
6	CR6	CR6-1 CR6-2	CP3A-3 CP3A-1	CR1 CR3
7	CR7	CR7-1 CR7-2	CP3A-3 CP3A-1	CR2 CR3
40	CR8	CR8-1 CR8-2	CP3A-3 CP3A-15	CR2 CR4
9	CR9	CR9-1 CR9-2	CP3A-1 CP3A-15	CR3 CR4

The combinational energization of relays CR1, CR2, CR3, CR4 for digits set up 5—9 corresponds to the code used in setting the K1—K4 relays, and, of course, is the same combination setting of the relays for storing the digits because such relays K1—K4 effected the selective energization of the storage relays.

During advancement of the card carriage to the seventeenth column position and each succeeding column position contacts 185 open and then close and an impulse is sent from wire 187 by wire 215 (Fig. 1f) to energize grounded relay coil D1. The latter closes its contacts D1—3 to energize grounded relay coil D2A. The latter closes its contacts D2A2 so as to transmit a delayed impulse from wire 215 to wire 229, (Figs. 1f, e, d, c, b, in order named) to wire 230, and through transferred CP3—1 contacts. Relay coil CP3 now being energized, its contacts CP3—2, 3, 4 and 5 are closed so that the impulse is transmitted to the movable blade of contacts CR1—1, CR2—1, CR3—1 and CR4—1, one or more being shifted according to the digit representation of the card column being analyzed. The latter contacts are in parallel with the contacts CK1—1, CK2—1, CK3—1, CK4—1 which are now at normal. Hence, the impulse is transmitted to lines 130, 1, 2, 3 and 4 if the movable blades of contacts CR1—1, CR2—1, CR3—1, CR4—1 are at normal but to lines 131, 1, 2, 3 and 4 if displaced, to send verifying impulses over the 76 lines in the manner previously described.

To compare such contact positions with the relay contacts 11-1, 12-1, 13-1, 14-1 of storage column No. 1, all of the AC1-4 relay contacts are shifted effected by energizing the AC relay at the seventeenth column position. At the seventeenth card column position brush 188 engaging contact point 189 at such position energizes relay coil AC by the wire connection 231, (Figs. 1f, e, d, c). If corresponding relay contacts CR1-1, CR2-1, CR3-1, CR4-1 and 11-1, 12-1, 13-1 and 14-1 are closed there is a determination that the card column punched corresponds in digital representation of the storage relays set up and which controlled punching in this card column. However, if any CR relay is set up under card control which does not agree with the relays set up in the compared storage column, an impulse is directed in the manner previously described to wire 132, (Fig. 1e) and thence through transferred CP3-8 contacts, through contacts E8A1 to SEA relay coil. Relay coil SEA closes its contacts SEA4 providing a circuit from line 105, switch 98, wire 99, SEA4 contacts, relay coil SE to ground. The latter closes its SE2 contacts in a local lamp circuit to light a signal lamp 240 indicating a non-check condition. Stick contacts SEA4 also provide the hold circuit back to the line 105 through manual switch 98. Referring now to Fig. 1g it is seen that upon an error relay contacts SE3 open and break the circuit to the trip magnet 77 to prevent ejection of the card even though checking operations for the card are completed for columns following the one punched incorrectly. In this manner the operator is informed of the error located by the checking procedure and steps can be taken to remove the erroneous card from the punch.

It will be noted from Fig. 1f that as the card carriage escapes column by column, brush 188 successively contacts contact points of the series 189 at column positions 17-27 successively energizing the other winding of duo coil relays AC to KC to effect the comparison of each perforated column with the related storage column in the manner described for the first comparison operation for column 17.

When card columns 17-20 are being punched, card columns 10-13 are being checked and concomitant with successive punching operations column spacing operations follow in the usual manner for the card punching machine. When the card carriage spaces to card column 21, automatic spacing of the card carriage follows, which it will be recalled, is effected in this instance by repeated energization of the punch magnet 66.

Successive impulses are effected by the brush 188 (Fig. 1f) in conjunction with the interconnected series of contact points 191 for columns 21, 22, 23, 25, 26, 27 and 28, noting that the contact point 191 of the series for column 24 is not connected with these. When the card carriage spaces to column 21, the brush 188 engages the contact point 191 at this column position to extend line 105 to a wire 141 (Fig. 1f) connected to grounded relay coil SR (Fig. 1g). The latter closes its contacts SR1 to transmit the impulse to punch magnet 66 and the card carriage spacing is effected and as the brush 188 leaves the contact point at column 21 the circuit is broken and the parts of the punching machine restored to normal. As the brush 188 engages the contact point at column 22, the circuit to relay SR is again closed and punch magnet 66 again energizes. It will be noted that from the wiring connections for contact points of columns 21 to 23,

this operation is repeated, thus spacing the card carriage step by step until column 24 is reached. Relay SR is preferably employed in the above circuit because direct energization of the punch magnet 66 might result in spacing speeds too rapid for satisfactory operation of the various relays which are energized as the card carriage spaces column by column.

When the card carriage spaces to column 24 a separate impulsing circuit is provided to impulse the SR relay described as follows: When the brush 188 strikes the contact point 189 at column 24 the relay coil HC (Fig. 1d) is energized for effecting the verification of storage column 8. This relay closes its contacts HC1 shown in Fig. 1f. When the brush 187 engages the contact point of the series 191 at column 24, relay coil CP4 (Fig. 1f) is energized as previously described, which relay coil closes its contacts CP4-13 shown in Fig. 1f. A circuit is now closed from the line 194 through relay contacts E4-2 now closed (Fig. 1d) to a wire 210 (Figs. 1d, 1e, 1f in the order named) to contacts CP4-13 now closed, thence through HC1 contacts to a wire 211 which is joined to the impulsing wire 141 (Figs. 1f and 1g) leading to the SR relay coil. Hence, by this supplemental circuit, relay coil SR is impaled to energize punch magnet 66 and effect spacing to column 25.

Thereafter, for columns 25, 26, 27 and 28 the circuit for effecting the successive impulsing of the SR relay to space the card carriage step by step is the same as previously described, it being noted that the cooperation of the brush 188 with the interconnected contact points 191 at columns 25, 26, 27 and 28 is effective for this supplemental carriage spacing operation. The carriage spaces from column 28 to the next card column at which time the skipping mechanism of the card carriage is effective to skip the card carriage to the last card column position.

It will be recalled that the relay coil CP3 (Fig. 1f) is picked up at card column position 17 and by the closure of its relay contacts shown in Fig. 45 1b it prepares the verifying circuits for checking of the first column of the storage circuit against the first card column analyzed, and verification for successive storage columns by comparison with the related punch card columns ensues for successive storage columns up to storage column 7 which time relay coil CP4 (Fig. 1f) is picked up at card column 24. Hence, relay coil CP4 transfers its contacts CP4-1 shown in Fig. 1b and also its contacts CP4-2-3-4 so that the verifying impulse is now directed from the line 229 to a line 228, thence through CP4-1 contacts now transferred and the CP4-2-3-4-5 contacts and the verifying impulse then extend through the CR contacts to lines 126 and 127 for verifying the digit set up in storage columns 8, 9, 10 and 11 in the manner previously explained.

Relay coil CP4 is preferably used for the transfer for the following reason: When storage column 10 is verified, punching of card columns 15, 65 16, 17 and 18 ensues (see Fig. 5). If only the CP3 relay is used this relay will not be energized to initiate checking of the card perforations until the key stroke for verification of storage column 11 is effected and this key operation might easily be delayed until after card columns 17 and 18 have been punched. This will result in the failure to check the perforations in card columns 10 and 11 which are checked simultaneously with the punching of card columns 17 and 18. This failure to check is prevented by having the CP3

relay transferred to impulse the punch checking circuits when card column 17 is reached and utilizing relay coil CP4, which is not energized until card column 24 is reached and the perforations in card column 17 are to be checked.

Release of storage columns after latter have been compared with the related card columns punched

After a sub-division of the storage columns has been compared with the related card columns, such storage columns are then released for the new setup by the operator. It will be noted from Fig. 5 that the release occurs at different times during the checking operations.

When storage columns 1 and 2 have been so utilized, the card carriage spaces to column 19, resulting in the energization of column relay CC (Fig. 1c), which energizing closes its contacts CC6 (Fig. 1b), closing a circuit from line 194 (which, it will be remembered, leads back to line 105) through E4-2 (Fig. 1d) relay contacts now closed, relay contacts CP3-13 now closed, wire 199 (Figs. 1d, e, f in the order named) through relay contacts CC6 to grounded relay coil DO1. The latter opens its contacts DO1-1 (Fig. 1c) releasing the hold circuits for storage columns 1 and 2. The operator can make a new digit setup in these two columns as is indicated in Fig. 5.

At card column position 22, storage column relay coil FC (Fig. 1d) energizes and the latter closes its contacts FC1 (Fig. 1f) to close a circuit from line 194, (which leads back to line 105), through E4-2 contacts now closed (Fig. 1d); wire 210 (Figs. 1d, e, f in the order named), through relay contacts FC1 (Fig. 1) to grounded relay coil DO2. The latter opens its contacts DO2-1 (Fig. 1d), releasing storage columns 3-5 for new digit setup. In the same manner, when the card carriage is at card column position 26, relay coil JC energizes to close its contacts JC8 (Fig. 1f) to close a circuit from line 210 to energize relay coil DO3 which opens its contacts DO3-1 (Fig. 1e) and release the storage column 6-9 for subsequent digit setup.

When the card carriage escapes to the twenty-eighth column position, brush 188 engages the 191 contact point at this position (see Fig. 1f) transmitting an impulse to relay coil DO4. The latter opens its stick contacts DO4-1, releasing storage columns 10 and 11 and also opens contacts DO4-2 (Fig. 1e) releasing the previously energized relay coils CP3, CP3A and CP4 and P2, P3 and P4. When the card carriage spaces to column 29, the conventional skipping mechanism comes into play so that the card carriage skips to the last column position, initiating the operation of the card ejecting mechanism of the punching machine provided that all of the card perforations have been found to be correct and agree in their digital representation with the digit set-ups of the compared storage columns.

Warning signal to indicate that storage columns are not cleared if an attempt is made to effect digit setup before storage columns are cleared

In the overlapping sequence in the machine it will be recalled that when contacts DO1-1 open, (Fig. 1c) storage columns 1 and 2 will be released, rendering them available for new storage operations. Relay coil P1 (Fig. 1c) remains energized until relay coil DO1 opens contacts DO1-1 to break the holding circuit for relay coil P1 to deenergize the latter so that while storage columns 1 and 2 are being utilized for the checking

operation relay contacts P1-2 are transferred from the position shown in Fig. 1c. Hence, an impulse sent to relay coil A transmitted as a result of a key stroke attempting to set up the 5 storage relays of column 1 is sent through relay contacts R3-7 (Fig. 1c) now in the position shown, through relay contacts P1-2 now transferred, wire 193 (Figs. 1c, b, a in the order named) to grounded relay coil F1. Relay coil F1 closes 10 its contacts F1-1, thereby closing a circuit from line 105, through lower relay contacts CB1 now closed thence by wire 125 to relay contacts F1-1 to relay coil F4. The latter closes its contacts F4-4 providing a stick circuit for the relay coil 15 F4 through such contacts thence through contacts E8-2 now in the position shown, to wire 136 connected to wire 99 which, it will be noted from Fig. 1f, extends back to the line 105 through switch 98. Relay coil F4 (Fig. 1a) closes its contacts F4-1 so that when CB1 contacts come back to normal upon the release of the depressed key, a circuit will be closed from line 105 through upper relay contacts CB1, thence by wire 134 through contacts F4-1 to grounded relay coil 20 BR. The consequent action of the energization of coil BR, it will be remembered, has the effect of sounding the buzzer on every subsequent key stroke until the operator releases the buzzer circuit by the opening of switch 98 (Fig. 1f). As a 25 further warning, relay coil F4 closes its contacts F4-2 (Fig. 1f) in a local lamp circuit of "not clear" lamp 255.

Relay coil BR opens its contacts BR1 (Fig. 1a) and BR2 (Fig. 1b) which, it will be recalled, has 30 the effect of disconnecting the storage circuits from the keyboard.

If relay coil P1 is deenergized at precisely the time that the entry is attempted in storage column 1 by a key stroke, the normal position of 40 relay contacts P1-2 prevents pickup of relay coil F1 and permits the operator to proceed with the digit entry, it being assumed that the punch will punch with sufficient rapidity to prevent the operator from overtaking the punch. Hence, 45 since the punch will be ahead of the operator the successive digit entries may proceed for remaining storage columns once the machine is conditioned for storage of digits.

Attention is directed to the provision of contacts E11-1 (Fig. 1a) which are in the nature of safety contacts provided for preventing misoperations as described as follows: The purpose of such contacts is to prevent undesired pickup of relay coil E8 under certain circumstances.

An example of this might be due to the circumstance that the carriage of the punching machine was not advanced sufficiently to energize relay coil DO1 so that contacts DO1-1 (Fig. 1c) are not open to deenergize relay coil P1 (Fig. 1c). 60 Hence, contacts P1-1 (Fig. 1a) would be in the transferred position.

By the circuit just described, it will be recalled that in the attempt of the operator to depress the key, relay coil BR would be energized which would close its contacts BR3. Therefore, an impulse will be sent from the line 105 through CB1 contacts now transferred, wire 125, thence through BR3 contacts and in the absence of the E11-1 contacts the impulse would be directed through P1-1 contacts now transferred, thence through R3A1 contacts now in the position shown, thence by wire 121 to relay coil E8. By the provision of contacts E11-1 which are normally open, it 75 will be seen that this impulse will not be trans-

mitted to effect the unwanted energization of relay coil E8.

Warning signal to operator upon exhaustion of cards in magazine

It is preferable to give a warning signal to the operator when cards in the magazine 53 (Fig. 4) of the punching machine have been exhausted and this expedient is well known and consists of contacts 175 (Fig. 1g) which are open whenever there is a card in the magazine 53. When the last card has been fed, pressure on the lower blade of the contacts 175 is relieved, thereby enabling contacts 175 to close, completing a circuit from the line 105 through contacts 175 thence by wire 176 (Figs. 1g, f, e, d, c, b, a, in the order named) to grounded relay coil F4. It will be recalled that the final consequence of the energization of the relay coil F4 will light the "not clear" lamp 255 (Fig. 1f) through F4—2 contacts and to pick up the buzzer relay BR (Fig. 1a) so that as previously described any subsequent key strokes will sound the "Buzzer."

Signal lights for indication of number of storage columns set up or verified

In order to provide the above indication, signal lights 260 (Fig. 1d), 261 and 262 (Fig. 1e) are provided and illuminated when storage columns 5, 9 and 11 have been set up or verified. The above indication is preferably divided according to the fields of the card shown in Fig. 3.

In the digit setup for storage columns 5 and 9, it will be observed that when column relays E and I for such storage columns close their H or hold contacts they will also connect the grounded lamps 260 and 261 back to the line 105 through the holding circuits for such relays.

With regard to the lighting of the lamp 262, it will be observed that the impulse line 250 (Fig. 1e) also transmits an impulse to the lamp 262, thereby flashing this lamp when a setup is made in storage column 11 or verification of this column is also effected. Operation of the motor bar at the end of verification also deenergizes the column relays E and I and consequently extinguishes lamps 260 and 261.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a punching machine, a plurality of sets of storage devices, punching mechanism controlled by the operated storage devices, keyboard controlled means for operating said storage devices for character representation thereby, comparing means operable by a repeated operation of the keyboard effected after the storage devices are operated and jointly controlled by the keyboard and the operated storage devices for detecting the correspondence or lack of correspondence between the operated storage devices and the repeat keyboard operation, means for effecting the operation of the punching mechanism under control of the verified storage devices to punch the character representation thereof on a sheet, means for analyzing the

75 punched information on the sheet, and verifying means under control of the analyzing means and the verified sets of the storage devices to determine a correspondence or lack of correspondence between the punched information and the original verified setting of the storage devices.

2. In a punching machine, the combination of a plurality of sets of storage devices, keyboard controlled means for setting up said storage devices to represent information to be punched, verifying means jointly controlled by said keyboard controlled means and said storage devices to verify the original setting of the storage devices by a reoperation of the keyboard, punching mechanism, means for effecting the operation of the punching mechanism under control of the verified sets of storage devices to punch the information represented thereby, means for analyzing the punched information on the sheet, and a supplemental verifying means under control of the analyzing means and the verified sets of the storage devices to determine a correspondence or variation in the punched information and the original setting of the storage devices, effected while the punching mechanism is operated to punch information under control of other of the sets of storage devices.

3. In a punching machine, the combination of a plurality of sets of storage devices, keyboard controlled means for setting up said storage devices to represent information to be punched, verifying means jointly controlled by said keyboard controlled means and said storage devices to verify the original setting of the storage devices by a reoperation of the keyboard, punching mechanism, initiating means for said punching mechanism to punch under control of the verified sets of the storage devices the information represented thereby while the keyboard is reoperated to verify other sets of the storage devices, means for analyzing the punched information on a sheet, and a supplemental verifying means under control of the analyzing means and the verified sets of storage devices to determine a correspondence or lack of correspondence between the punched information and the original setting of the storage devices.

4. In a punching machine, the combination of a plurality of sets of storage devices, keyboard controlled means for setting up said storage devices to represent information to be punched, means for maintaining the storage devices in set condition, verifying means jointly controlled by said keyboard controlled means and said storage devices to verify the original setting of the storage devices by a reoperation of the keyboard, punching mechanism, initiating means for said punching mechanism to punch under control of the verified sets of the storage devices the information represented thereby while the keyboard is reoperated to verify other sets of the storage devices, means for analyzing the punched information on a sheet, a supplemental verifying means under control of the analyzing means and the verified sets of the storage devices to determine a correspondence or lack of correspondence between the punched information and the original setting of the storage devices, and means for disabling said maintaining means for the storage devices determined to be correct in their original setting, whereby such released storage device can again be set up by the operator while supplemental verifying operations are being effected for other of the storage devices.

5. In a punching machine, the combination of

a plurality of sets of storage devices, keyboard controlled means for setting up said storage devices to represent information to be punched, means for maintaining the storage devices in set condition, verifying means jointly controlled by said keyboard controlled means and said storage devices to verify the original setting of the storage devices by a reoperation of the keyboard, punching mechanism, initiating means for said punching mechanism to punch under control of the verified sets of the storage devices the information represented thereby, means for analyzing the punched information on a sheet, a supplemental verifying means under control of the analyzing means and the verified sets of the storage devices to determine a correspondence or lack of correspondence between the punched information and the original setting of the storage devices, while the punching mechanism is operated to punch information under control of other of the sets of verified storage devices, and means for disabling the maintaining means for the storage devices determined to be correct in their original setting, whereby such released storage devices can again be set up by the operator while supplemental verifying operations are being effected under control of the other of the storage devices.

6. In a punching machine, the combination of a plurality of sets of storage devices, keyboard controlled means for setting up said storage devices to represent information to be punched, means for maintaining the storage devices in set condition, verifying means jointly controlled by said keyboard controlled means and said storage devices to verify the original setting of the storage devices by a reoperation of the keyboard, punching mechanism, initiating means for said punching mechanism to punch under control of the verified sets of the storage devices the information represented thereby, means for analyzing the punched information on a sheet, a supplemental verifying means under control of the analyzing means and the verified sets of the storage devices to determine a correspondence or lack of correspondence between the punched information and the original setting of the storage devices, and means for disabling said maintaining means upon the supplemental verifying means determining that the verified sets of storage devices correspond to the punched information, whereby such storage devices can be reset by the keyboard.

7. In a punching machine, the combination of a plurality of storage devices arranged in subdivisions, keyboard controlled means for setting up said storage devices to represent information to be punched, verifying means jointly controlled by said keyboard controlled means and said storage devices to verify the original setting of the storage devices by a reoperation of the keyboard, punching mechanism, initiating means for said punching mechanism to punch under control of each sub-division of the storage devices verified as correct in its setting the information represented thereby while the keyboard is reoperated to verify a subsequent subdivision of the storage devices, means for analyzing the punched information on a sheet, and a supplemental verifying means under control of the analyzing means and the verified sub-division of the storage devices to determine a correspondence or lack of correspondence between the punched information and the original setting of the storage devices which controlled the punching mechanism, while the punching mechanism is being operated to punch

information under control of other of the verified storage devices.

8. In a punching machine, the combination of a plurality of sets of storage devices, keyboard controlled means for setting up said storage devices to represent information to be punched, verifying means jointly controlled by said keyboard controlled means and said storage devices to verify the original setting of the storage devices by a reoperation of the keyboard, punching mechanism, initiating means for said punching mechanism to punch under control of the verified sets of the storage devices the information represented thereby while the keyboard is reoperated to verify other sets of the storage devices, means for analyzing the punched information on a sheet, and a supplemental verifying means under control of the analyzing means and the verified sets of the storage devices to determine a correspondence or lack of correspondence between the punched information and the original setting of the storage devices, while the punching mechanism is operated to punch information under control of other of the sets of verified storage devices.

9. In a punching machine, the combination of a plurality of sets of storage devices, keyboard controlled means for setting up said storage devices to represent information to be punched, means for retaining said storage devices in such information representing condition, verifying means jointly controlled by said keyboard controlled means and the said storage devices to verify the original setting of the storage devices by a reoperation of the keyboard, punching mechanism, initiating means for said punching mechanism to punch under control of the verified sets of the storage devices the information represented thereby while the keyboard is reoperated to verify other sets of the storage devices, means for analyzing the punched information on a sheet, supplemental verifying means under control of the analyzing means and the verified sets of storage devices to determine a correspondence or variation between the punched information and the original setting of the storage devices, effected while the punching mechanism is operated to punch information under control of the sets of verified storage devices, and means for disabling the maintaining means for the sets of storage devices which have been determined to be correct in their original setting after the supplemental verifying operation whereby said released sets of storage devices can be set up by a keyboard operation effected while the supplemental verifying means is operable to verify the original setting of others of the verified storage devices against the related punched information.

10. In a punching machine, the combination of a plurality of sets of storage devices, keyboard controlled means for setting up said storage devices in combination to represent information to be punched, verifying means jointly controlled by said keyboard controlled means and said storage devices to verify the combinational setting of the storage devices by a reoperation of the keyboard, punching mechanism, translating means under control of the said storage devices for operating said punching mechanism to punch under control of the verified sets of the storage devices the information represented thereby according to the Hollerith code, means for analyzing the punched information on a sheet, means for converting and representing the Hollerith code punched representation to a combinational setting correspond-

ing to the combinational setup of the storage devices, and a supplemental verifying means under control of the last named representing means and the verified sets of the storage devices to determine a correspondence or lack of correspondence between the punched information and the original setting of the storage devices.

11. In combination, a plurality of storage devices, a punching mechanism controlled by said storage devices, manually controlled means for setting up said storage devices, verifying means operative upon completion of setting said storage devices jointly controlled by said storage devices and the manually controlled means for verifying the setting of the storage device by reoperation of the manually controlled means, and overlap means whereby upon completion of verification of some of the storage devices the punching mechanism may be operated in accordance with the verified storage devices while said manually controlled means are being reoperated to verify other storage device.

12. In combination, punches of a punching machine, electromagnetically controlled punch selecting mechanism, keyboard controlled means for setting said punch selecting mechanism, verifying means under control of said punch selecting mechanism and the keyboard controlled means to verify the setting of the punch selecting mechanism by reoperation of the keyboard, and means for operating the punches of the punching machine under control of the verified punch selecting mechanism while the keyboard is being reoperated for the verification of other punch selecting mechanism.

13. In a punching machine, the combination of a plurality of storage devices arranged in sub-divisions, key controlled means for setting up said storage devices, verifying means controlled jointly by the key controlled means and the storage devices for verifying the setup of each sub-division of the storage devices and repeat keyboard operations, punching mechanism controlled by the storage devices, and means for causing the operation of the punching mechanism under control of the verified sub-division of storage devices upon completion of the verification of each sub-division.

14. In a punching machine, the combination of a plurality of storage devices arranged in sub-divisions, key controlled means for setting up said storage devices, punching mechanism for punching a card, field by field, under control of the verified sub-division of storage devices, verifying means controlled jointly by the key controlled means and the storage devices for verifying the setting of each sub-division of the storage devices and the repeat keyboard operations, and means for causing the punching mechanism to punch a field of the card under control of each verified sub-division and terminate the operation of the punching mechanism until a subsequent sub-division of storage devices have been verified to control punching of a subsequent field.

15. In a punching machine, the combination of a plurality of sets of storage devices, keyboard controlled means for setting up said storage devices and retaining the latter set up to represent information to be punched, punching mechanism controlled by said storage devices, verifying means comprising comparing means operative after the storage devices are set up and jointly controlled by the storage devices set up and the keyboard controlled means for determining a variation or correspondence in the setting of the storage de-

vices and the repeat keyboard operations, and means operative upon the verifying means indicating a complete correspondence with respect to the setting of all the sets of storage devices and the repeat keyboard operation for initiating an operation of the punching mechanism to punch under control of the setup storage devices the information represented thereby.

16. In a punching machine, the combination of 10 a plurality of sets of storage devices arranged in sub-divisions, keyboard controlled means for setting up said storage devices and retaining the latter set up to represent information to be punched, verifying means comprising comparing 15 means operative after the storage devices are set up and jointly controlled by the setup storage devices and the keyboard controlled means for determining a variation or correspondence in the setting of the storage devices in each sub-division 20 and the repeat keyboard operations, punching mechanism controlled by the storage devices for punching information represented thereby, and a plurality of punch initiating control means, one for each sub-division of the storage devices and each operative upon the verification of all the storage devices of the related sub-division and indication of correspondence to automatically initiate punching operations of the punching mechanism under control of the verified sub-division of 30 storage devices.

17. In a punching machine, the combination of 35 plurality of storage devices arranged in sub-divisions, key controlled means for setting up said storage devices, verifying means controlled jointly by the key controlled means and the storage devices for verifying the setup of each sub-division of the storage devices and repeat keyboard operations, punching mechanism controlled by the storage devices, and means for causing upon the 40 completion of the verification of each sub-division, and the repeat keyboard operation for verifying the first column of the next higher sub-division, the operation of the punching mechanism under control of the previously verified sub-division of the storage devices.

18. In a punching mechanism, the combination of 45 a plurality of storage devices arranged in sub-divisions, key controlled means for setting up said storage devices, verifying means controlled jointly by the key controlled means and the storage devices for verifying the setup of each sub-division of the storage devices and repeat keyboard operations, variably operated clearout means for 50 said storage devices to selectively clear out the sub-division in which said verifying means detects an error, and the higher unverified sub-divisions, punching mechanism controlled by storage devices to punch the information represented thereby, and means for causing upon the 55 completion of the verification of each sub-division found to be correct, and the keyboard operation for verifying the first column of the next sub-division, the operation of the punching under control of the storage devices found to be initially 60 correct, or corrected after an error has been detected and the storage devices have been reset and again verified by said verifying means.

19. In a punching machine, the combination of 65 a plurality of storage devices arranged in sub-divisions and set up in combination, means comprising digit keys 0-9 and combinational setup means controlled thereby for setting up said storage devices in combination, means controlled by said storage devices and said combinational setup means for verifying upon repeat key operations

of keys 0—9 the combinational setting of each sub-division of the storage devices and the combinational setup means operated by repeat key operations, punching mechanism, translating means controlled by each of said storage devices for converting the combinational setup to a Hollerith code representation for controlling said punching mechanism for punching according to said Hollerith code, and means for initiating upon the verification of each sub-division of the storage devices the operation of said punching mechanism under control of the translating means associated with the verified sub-division of storage devices.

20. In a punching machine, a plurality of storage devices arranged in sub-divisions, a keyboard comprising key controlled means for setting up said storage devices, verifying means jointly controlled by said storage devices and the key controlled means for verifying the setting of each sub-division of the storage devices and repeat keyboard operations, means operative upon completion of verification of each sub-division of storage devices, and the keyboard operation for verifying the first column of the next sub-division to be verified, for punching a representation of the information set up in the verified sub-division of storage devices, and means controlled by said comparing means upon detecting an error in the setting of the storage devices being verified for rendering said key controlled means inoperative to effect the keyboard operation for verifying the first column of the next sub-division to be verified, and thereby prevent the punching operation under control of a sub-division found to have an error in its setting.

21. In a punching machine, the combination of a plurality of storage devices arranged in sub-divisions, keyboard controlled means for setting up said storage devices to represent information to be punched, punching mechanism, initiating means for said punching mechanism to punch under control of each sub-division of the storage devices the information represented thereby, means for analyzing the punched information on a sheet, verifying means jointly under control of the analyzing means and each sub-division of the storage devices to determine a correspondence or lack of correspondence between the punched information and the original setting of the storage devices, and overlapping means to effect the operation of the verifying means while the punching mechanism is operated to punch information under control of other sub-divisions of the storage devices.

22. In a punching machine, the combination of a plurality of storage devices arranged in sub-divisions, keyboard controlled means for setting up said storage devices to represent information to be punched, means to maintain the storage devices in set condition, punching mechanism, initiating means for said punching mechanism to punch under control of each sub-division of the storage devices the information represented thereby, means for analyzing the punched information on a sheet, verifying means under control of the analyzing means and each sub-division of the storage devices to determine a correspondence or lack of correspondence between the punched information and the original setting of the storage devices, including means to effect the operation of the verifying means while the punching mechanism is operated to punch information under control of other of the storage devices, and means to disable the maintaining

means of the sub-division of the storage devices verified as correct, whereby the keyboard may be operated to again set up the released sub-division of storage devices.

5 23. In a punching machine, the combination of a plurality of storage devices arranged in sub-divisions, keyboard controlled means for setting up said storage devices in a combinational code to represent information to be punched, punching mechanism, translating means under control of said storage devices for causing said punching mechanism to punch under control of each sub-division of the storage devices the information represented thereby in another code, means for 10 analyzing the punched information on a sheet, means for translating and converting the analysis to the aforesaid combinational code representation, and verifying means under control of the last named means and each sub-division of the 15 storage devices to determine a correspondence or lack of correspondence between the punched information and the original setting of the storage devices.

20 24. In a punching machine, the combination of a plurality of sets of storage devices, keyboard controlled means for setting up said storage devices to represent information to be punched, punching mechanism, initiating means for said punching mechanism to punch under control of the sets of the storage devices the information represented thereby, means for analyzing the punched information on a sheet, verifying means under control of the analyzing means and the sets of the storage devices to determine a correspondence or lack of correspondence between the punched information and the original setting of the storage devices, and overlapping means to 25 initiate and effect the operation of the verifying means while the punching mechanism is operated to punch information under control of other of the sets of storage devices.

30 25. In a punching machine, a plurality of sets of storage relays, a punching mechanism controlled by said storage relays, keyboard controlled means for operating and setting up said relays, and comparing means operable by a repeated operation of the keyboard effected after the storage relays are operated and jointly controlled by the operated storage relays and said keyboard controlled means for detecting the correspondence or lack of correspondence between the operated storage relays and the repeat keyboard operation.

35 26. In a punching machine, a plurality of sets of storage relays, a punching mechanism controlled by the operated storage relays, keyboard controlled means for operating said storage relays for character representation thereby, and comparing means operable by a repeated operation of the keyboard effected after the storage relays are operated and jointly controlled by the keyboard and the operated and non-operated storage relays for detecting the correspondence or 40 lack of correspondence between the operated storage relays and the repeat keyboard operation.

45 27. In a punching machine, a plurality of sets of denominational ordered storage devices, punching devices controlled by said storage devices, keyboard controlled means for setting up said storage devices to represent digits, supplemental setup means controlled by said keyboard for indicating a digit corresponding to a repeat keyboard operation effected after the storage devices are set up, means for comparing the digit indication on the supplemental setup means ef-

fected by the first repeat keyboard operation with the setting in the first set of storage devices and thereafter comparing successive digit settings on the remaining sets of storage devices with each digit indication on the supplemental setup means effected by successive repeat keyboard operations, and means controlled by the comparing means for signifying a variation in the digit indication on the supplemental setup means and the compared set of storage devices.

28. In a punching machine, a plurality of sets of denominational ordered storage devices, punching devices controlled by said storage devices, keyboard controlled means for setting up said storage devices and retaining the setting to represent digits, supplemental setup means controlled by said keyboard for indicating a digit corresponding to a repeat keyboard operation effected after the storage devices are set up, means for coordinating said sets of storage devices for comparison with said supplemental setup means in succession, and comparing means operative upon each repeat keyboard operation effected for setting up said supplemental setup means, for comparing the digit indication on the supplemental setup means with the digit setting on the compared set of storage devices.

29. In a punching machine, a plurality of sets of denominational ordered storage devices, punching devices controlled by said storage devices, keyboard controlled means for transmitting digit representing impulses to said storage devices for setting up said storage devices in succession to represent digits, supplemental setup means controlled by said keyboard for indicating a digit corresponding to a repeat keyboard operation effected after the storage devices are set up, means for coordinating said sets of storage devices with said supplemental setup means in succession, and comparing means operative upon each repeat keyboard operation effected after the storage devices are set up for transmitting under control of the supplemental means set up by that repeat keyboard operation verifying digit representing impulses to determine whether the compared storage devices correspond in digit setting to the digit setting of the supplemental setup means.

30. In a punching machine, a plurality of sets of denominational ordered storage devices, punching devices controlled by said storage devices, keyboard controlled means for transmitting digit representing impulses to said storage devices for setting up said storage devices in succession to represent digits, supplemental setup means controlled by said keyboard for indicating a digit corresponding to a repeat keyboard operation effected after the storage devices are set up, means for coordinating said sets of storage devices with said supplemental setup means in succession, and comparing means operative upon each repeat keyboard operation effected after the storage devices are set up for transmitting under control of the supplemental means set up by that repeat keyboard operation verifying digit representing impulses to determine whether the compared storage devices correspond in digit setting to the digit setting of the supplemental setup means, and means rendered operative by the verifying impulse detecting a non-correspondence in the digit setting of the compared storage devices with the supplemental digit setup means for signifying such fact.

31. In a punching machine, a plurality of sets of denominational ordered storage devices, punch-

ing devices controlled by said storage devices, keyboard controlled means for setting up said storage devices to represent digits, supplemental setup means for indicating digits, means operative upon setting up all of the sets of storage devices to coordinate said keyboard control setting means with said supplemental setup means for causing each repeat keyboard operation effected after the storage devices are set up to indicate a digit corresponding to the repeat keyboard operation, means for comparing the digit indication on the supplemental setup means with the setting on the first set of storage devices and thereafter comparing successive digit settings on the remaining sets of storage devices with each digit indication on the supplemental setup means effected by successive keyboard operations, and means controlled by the comparing means for signifying a variation in the digit indication on the supplemental setup means and the compared set of storage devices.

32. In a punching machine, a plurality of sets of denominational ordered storage devices, punching devices controlled by said storage devices, a plurality of keys, means controlled by said keys for successively setting up said storage devices to represent digits, said setting means including sequencing means to coordinate said sets of storage devices in succession with said keys for causing the successive setting of the storage devices, supplemental setup means controlled by said keys for indicating a digit corresponding to the repeat key operation effected after the storage devices are set up, means for comparing the digit indication on the supplemental setup means with the setting in the first set of storage devices and thereafter by the operation of said sequencing means coordinating said supplemental setup means with the remaining set of storage devices in succession for comparing each digit indication on the supplemental setup means effected by repeat operation of the keys with the setup on the compared storage devices, and means controlled by the comparing means for signifying a variation in the digit indication on the supplemental setup means and the compared set of storage devices.

33. In a punching machine, a plurality of sets of denominational ordered storage devices, keyboard controlled means including sequencing means rendered operative by keyboard operations for successively setting up said storage devices to represent digits, supplemental setup means, means operative upon setting up all the sets of storage devices to coordinate said keyboard with said supplemental setup means for causing each repeat keyboard operation effected after the storage devices are set up to indicate a digit corresponding to the repeat keyboard operation, means for comparing the digit indication on the supplemental setup means with the setting on the first set of storage devices and thereafter under control of said sequencing means comparing successive digit settings on the remaining set of storage devices with each digit indication on the supplemental means effected by successive repeat keyboard operations, and means controlled by the comparing means for signifying a variation in the digit indication on the supplemental means and the compared set of storage devices.

34. In a punching machine, a plurality of sets of denominational ordered storage devices, punching devices controlled by said sets of storage devices, keyboard controlled means for setting up said storage devices to represent digits,

supplemental setup means controlled by said keyboard for indicating a digit corresponding to a repeat keyboard operation effected after the storage devices are set up, means for comparing the digit indication on the supplemental setup means with the setting in the first set of storage devices and thereafter comparing successive digit settings on the remaining sets of storage devices with each digit indication on the supplemental setup means effective by successive repeat keyboard operations, an audible signalling means, and interconnecting means controlled by said comparing means for coordinating said keyboard with said audible signalling means whereby after the comparing means has detected a variation in the digit indication on the supplemental setup means and the compared set of storage devices said audible signalling means will be operated for each subsequent key stroke effected after an error has been detected.

35. In a punching machine, the combination of a plurality of sets of punch selecting storage relays, a keyboard, means controlled by said keyboard for energizing said sets of relays in succession, and upon energizing each set of storage relays for energizing a related column entry control relay for coordinating the next set of storage relays to be energized with said keyboard and upon the next set of storage relays being energized the related column entry control relay is energized to effect the function described and to disconnect the next lower set of energized relays from the keyboard, means for retaining the energized sets of relays energized and the related column entry control relays, and means operable at the will of the operator for disabling said retaining means for deenergizing the energized column entry control relays and the energized sets of storage relays to clear the latter of the information represented thereby.

36. In a punching machine, a plurality of storage relays, a punching mechanism controlled by the energized storage relays, keyboard controlled means for energizing said relays, means for retaining the relays energized for retention of representation of information to be punched, comparing means operable by a repeated operation of the keyboard effected after the storage relays are energized and jointly controlled by the energized storage relays and the keyboard controlled means for detecting the correspondence or lack of correspondence between the energized storage relays and the repeat keyboard operation, and means operative at the will of the operator for rendering said retaining means ineffective whereby said storage relays are conditioned to normal.

37. In a punching machine, a plurality of sets of storage devices, a punching mechanism controlled by the operated storage devices, keyboard controlled means for setting up and operating said storage devices, means for retaining said storage devices in setup condition for retaining a representation of information to be punched, comparing means operable by a repeated operation of the keyboard effected after the storage devices are set up and jointly controlled by the storage devices and the keyboard controlled means for detecting the correspondence or lack of correspondence between the storage devices previously set up and the repeat keyboard operation, and means operable at the will of the operator for disabling said retaining means to condition the storage devices to a non-operated position.

38. In a punching machine, a plurality of sets of storage devices arranged in ordered sub-divisions, keyboard controlled means for setting up said storage devices and retaining them set up to represent information to be punched, comparing means jointly controlled by the storage devices and the keyboard controlled means for verifying upon a repeat keyboard operation the setting up of the information in each sub-division for detecting a possible error in a particular sub-division, and a disabling means for said storage devices variably operated in accordance with the sub-division an error was ascertained for clearing out that sub-division of storage devices and without clearing out those lower order sub-divisions already verified as correct in their represented information.

39. In a punching machine, a plurality of sets of storage devices arranged in ordered sub-divisions, keyboard controlled means for setting up said storage devices and retaining them set up to represent information to be punched, comparing means jointly controlled by the storage devices and the keyboard controlled means for verifying upon a repeat keyboard operation the setting up of the information in each sub-division for detecting a possible error in a particular sub-division, and a disabling means for said storage devices variably operated in accordance with the sub-division an error was ascertained for clearing out that sub-division of storage devices and unverified sub-divisions higher in order and without clearing out those lower order sub-divisions already verified as correct in their represented information.

40. In a punching machine, a plurality of sets of storage relays arranged in ordered sub-divisions, keyboard controlled means for energizing said storage relays and retaining them energized to represent information to be punched, comparing means jointly controlled by the storage relays and the keyboard controlled means for verifying upon a repeat keyboard operation the representation of the information in each sub-division for detecting a possible error in a particular sub-division, and means for deenergizing said storage relays variably operated in accordance with the particular sub-division an error was ascertained for clearing out that sub-division of storage relays and without clearing out those lower order sub-divisions already verified as correct in their represented information.

41. In a punching machine, a plurality of sets of storage devices arranged in ordered sub-divisions, keyboard controlled means for setting up said storage devices and retaining them set up to represent information to be punched, comparing means jointly controlled by the storage devices and the keyboard controlled means for verifying upon a repeat keyboard operation the setting up of the information in each sub-division for detecting a possible error in a particular sub-division, an error key and disabling means for said storage devices set in operation by said error key and variably operated in accordance with the sub-division an error was ascertained for clearing out that sub-division of storage devices and without clearing out those lower order sub-divisions already verified as correct in their represented information.

42. In a punching machine, a plurality of sets of storage devices arranged in ordered sub-divisions, keyboard controlled means for setting up said storage devices and retaining them set up to represent information to be punched, comparing

means jointly controlled by the storage devices and the keyboard controlled means for verifying upon a repeat keyboard operation the setting up of the information in each sub-division for detecting a possible error in a particular sub-division, separate disabling means for each sub-division of said storage devices for clearing out the related sub-division of its representation, and selective means operable in dependence upon the number of sub-divisions verified and the particular sub-division the error was ascertained for operating the disabling means for that sub-division and without operating the disabling means for the verified sub-divisions lower in order.

43. In a punching machine, a plurality of sets of storage devices arranged in ordered sub-divisions, keyboard controlled means for setting up said storage devices and retaining them set up to represent information to be punched, comparing means jointly controlled by the storage devices and the keyboard controlled means for verifying upon a repeat keyboard operation the setting up of the information in each sub-division of the storage devices, means operative upon the completion of the setting up of all sub-divisions of the storage devices to render said comparing means operable, and a disabling means rendered operable by said last named means for said storage devices variably operated in accordance with the sub-division an error was ascertained for clearing out that sub-division and without clearing out those lower order sub-divisions already verified as correct in their represented information.

44. In a punching machine, a plurality of sets of storage devices arranged in ordered sub-divisions, keyboard controlled means for setting up said storage devices and retaining them set up to represent information to be punched, disabling means for clearing out all sub-divisions of said storage devices when an error has been detected before subsequent verification thereof, compar-

ing means jointly controlled by the storage devices and the keyboard controlled means for verifying upon a repeat keyboard operation the setting up of the information in each sub-division of the storage devices, means operative upon the completion of the setting up of all sub-divisions of the storage devices to render said comparing means operable, and a selective means rendered operable by said last named means for variably operating said disabling means in accordance with the particular sub-division an error was ascertained for clearing out that sub-division, and without clearing out those lower order sub-divisions already verified as correct in their represented information.

45. In a machine of the class described, a plurality of storage devices for controlling recording operations, keyboard controlled means for operating and setting up said storage devices as the keys thereof are operated, and comparing means operable by a repeated operation of the same keyboard effected after the storage devices are operated and jointly controlled by the operated storage devices and said keyboard controlled means for detecting as the keyboard operation is repeated the correspondence or lack of correspondence between the operated storage devices and the repeat keyboard operation.

46. In a machine of the class described, a plurality of sets of storage devices for controlling recording operations, keyboard controlled means for operating said storage devices for character representation thereby, and comparing means operable by a repeated operation of the keyboard effected after the storage devices are operated and jointly controlled by the keyboard and the operated and non-operated storage devices for detecting the correspondence or lack of correspondence between the operated storage devices and the repeat keyboard operation.
